UNITED STATES PATENT OFFICE

2,359,853

PRINTING MACHINE

Carl J. Hueber, Euclid, Ohio, assignor to Addressograph-Multigraph Corporation, Wilmington, Del., a corporation of Delaware

Application September 8, 1941, Serial No. 410,097

50 Claims. (Cl. 101—56)

This invention relates to printing machines of the kind through which printing devices are passed seriatim to a printing position in the machine whereat printing impressions are made from the printing devices upon a sheet or the like, and more particularly the invention relates to the distribution of the impressions from such printing devices so that various selected parts of the data carried by a particular printing device are printed upon the form in a relationship which is different than the arrangement of such parts on the printing device.

In the use of printing machines of the aforesaid character it is customary to employ printing devices having a series of lines of printing characters disposed upon the printing device with the lines one above the other in what may be termed a single column, and the printing impressions are usually made from the printing characters on the printing device so that these printing characters are printed upon the sheet or form in precisely the same arrangement. Such printing machines are so constructed that the printing devices are withdrawn one by one from a supply magazine and are advanced in a step-by-step manner to a printing position in the machine. At such printing position, the sheet or form is disposed in the desired relationship to the printing device and while the printing device remains stationary at printing position a suitable impression means is operative to make the desired printing impressions from the type characters of the printing device onto the sheet. Various arrangements have heretofore been provided whereby selected portions of the type characters carried on a printing device might be printed to the exclusion of other type characters, and hence the printing devices in many instances may embody considerable information pertaining to a particular subject or person, and selected parts of this information may be printed as desired. The information carried by the printing devices is advantageously arranged so that it is adaptable for the most common uses to which such printing devices may be put. Thus, for example, a printing device may embody the name, the street address and the city and State of residence of a person to which a particular device relates, and in addition there may be a fourth line of type characters constituting a salutation whereby the name and address data and the salutation may be printed upon a letter which is to be sent to the particular person to which the printing device pertains. Further or different data may of course be embodied in such a printing device

either at the ends of the lines in which the aforementioned data are embodied, or in additional lines of type characters or in special applications, numerical and other data may be included on the device.

While such printing devices are ordinarily used to print the data onto a sheet or form in the same arrangement in which such data are found on each printing device, there are certain applications or uses for such printing devices wherein it is desirable to distribute the various lines or classes of data carried on each printing device in a different relationship upon the sheet or form. For example, a particular business form may embody a plurality of columns and the user may desire to print in one column of such a form the information or data of one class carried by a printing device and to print in another column the information of another class of data carried by the printing device. This is known in the art as multiple column or distributing listing, and it usually involves the distribution of the different classes of data from the printing devices in two, three or more columns, usually in side-by-side relation. In all such listing it may be desired to print one or more lines of type characters in each or selected ones of the columns, and where more than one line of type characters is printed from a single printing device in a particular column it is customary to refer to such type matter as a group or a group of lines of type characters.

As one example, it may be desirable to print merely the first line of type characters from a printing device in the first or left-hand column of the sheet or form, and to print all of the address data, that is, the street address and the city and State, in the second or right-hand column of the form. In most instances the street address would be arranged on the printing device in one line of type characters while the city and State would be arranged in the next line of type characters on the printing device, so that in such an instance a group of lines would be printed in the second or right-hand column. It will be recognized of course that this distribution is merely illustrative and might in many instances be reversed or modified to meet varying requirements imposed by the use to which the form is to be put.

Many variable factors are involved in the attainment of the desired distribution and selection of the type characters to be printed upon a multiple column form, and it is the primary object of the present invention to simplify and

facilitate the attainment of the desired selection and distribution of the printing impressions in multiple column listing.

The performance of multiple column or distributive listing on a printing machine of the aforesaid character must take into account the different line or group spacings which may be desired in the different types of forms which may be encountered, as well as the different column spacings, the different and widely varying top and bottom margins which may be desired upon such forms, and the different selection of lines to be printed from each printing device. In addition to the foregoing it will be recognized that the lines of type characters on the printing devices may vary considerably as to line spacing when different types of printing devices are encountered, and in some instances different line spacings may be used between the lines of type characters on a particular printing device. In this connection, however, it should be observed that in a particular run of printing devices through a printing machine it is customary to use printing devices of the same character and design and having the same line spacing arrangement, but in different runs of the machine it may be desirable to employ different groups of printing devices embodying different line spacing arrangements and to enable this to be accomplished is another object of this invention.

It is also another important object of the present invention to enable a wide variety of varying conditions to be met with a multiple column lister of a particular design, and further objects related to the foregoing are to enable such varying conditions to be met through adjustment of the machine by the usual operator thereof rather than by a skilled service man, and to enable the adjustments which are made in the apparatus to be preserved even though the listing mechanism is removed from the printing machine for the purpose of enabling the printing machine to be utilized for the performance of other classes of printing.

Another object of the invention is to simplify the association of a multiple column listing mechanism with a printing machine.

A further object of the invention is to provide a multiple column listing apparatus which may be readily adapted for reversing the normal distribution or columnar printing of the data on the sheet or form.

Another object of the invention is to provide multiple column listing apparatus which is adapted to cooperate with selector means in the printing machine with which it is associated to thereby enable uniform arrangement of the printed matter on a sheet or form to be attained despite skipping of printing devices under the control of the selector mechanism.

A further object is to enable the operation of a printing machine and an associated multiple column lister to be automatically stopped in a novel manner when the last printing impression has been made in the last line of the form, and an object related to the foregoing is to enable both the top and bottom margins on a form to be automatically controlled by the multiple column lister.

When such a distributing or multiple column lister is operated in timed relation to the operation of the printing machine it is often desirable to skip a particular line or space in the columns of the form, and another object of the invention is to enable such spacing of the form to be at-

tained, and a related object is to enable this to be effected manually.

A further object of the present invention is to provide an automatic distributing lister whereby the printing characters or type matter carried on the printing devices may be readily distributed in three different columns on a form, and an object related to the foregoing is to enable such three column distribution to be attained in a distributing lister which is produced through but a slight modification of a lister designed and built primarily for the performance of two column listing operations.

Other objects of the invention are to provide a multiple column lister which is unitary in character and which may be simply and easily mounted upon or removed from a printing machine; to so construct such a lister that the various operative movements of the parts thereof are effected through but a single operative or driving connection with the driving means of the printing machine; to utilize cams for the attainment of the desired line spacing operations of the paper holder of such a multiple column lister, and to so locate such cams as to facilitate changes in the adjusted relationship thereof; to attain proper alignment of the related lines of type characters printed in different columns of the form through the use of a plurality of independently adjustable spacing or actuating mechanisms for the paper holder; to effect longitudinal movement of the sheet or form in a multiple column lister in both advancing and back spacing directions; to provide independently actuatable sheet advancing and back spacing means in such a lister; to enable the strokes of the line spacing and back spacing means to be independently adjusted or varied; to condition the line spacing means of such a multiple column lister for a succeeding line spacing or sheet advancing movement during a period when the sheet is being retracted for purposes of aligning the related lines of type in different columns; and to so construct such a multiple column lister that a basic embodiment thereof may be readily modified to provide for either hand spacing of the form or for the distribution of the printed matter in a varying number of columns.

Other and further objects of the present invention will be apparent from the following description and claims and will be understood by reference to the accompanying drawings which, by way of illustration, show preferred embodiments and the principle thereof and what I now consider to be the best mode in which I have contemplated applying that principle. Other embodiments of the invention embodying the same or equivalent principles may be used and structural changes may be made as desired by those skilled in the art without departing from the present invention and the purview of the appended claims.

of the invention which enables hand or manual spacing of the form to be attained;

Fig. 28 is a vertical sectional view taken substantially along the line 28—28 of Fig. 27;

Fig. 29 is a fragmental plan view similar to Fig. 2 and illustrating another embodiment of the invention whereby the lines of data carried on a printing device may be distributed in three different columns on a form rather than in two columns;

Fig. 30 is a fragmental plan or front face view of a form embodying three columns and adapted for use in connection with the three column lister shown in Fig. 29;

Fig. 31 is an enlarged portion of Fig. 30; and

Fig. 32 is a fragmental portion of a printing device similar to that shown in Fig. 23 and illustrating one arrangement of the lines of type characters which may be employed in the three column listing work.

General description

In the form chosen for disclosure in Figs. 1 to 26, inclusive, the invention is embodied in a printing apparatus comprising a printing machine 40 having a multiple column listing device 41 operatively associated therewith in such a manner that through automatic shifting of a sheet such as the form F by the listing device 41 in timed relation to the operation of the printing machine 40, the data embodied in the printing means of a printing device D, Fig. 23, may be distributed in a multiple column relationship on the form F despite the single column arrangement of such data on the printing device. The multiple column listing device 41 of the present invention is unitary in character and is constructed and related to the printing machine 40 in such a manner that the listing device 41 may be readily and easily placed in an operative association with the printing machine or may be quickly and easily removed from such operative association when the operator wishes to use the printing machine 40 for other classes of printing work. The multiple column listing device 41 is so constructed and arranged that it may be adjusted readily and easily to perform listing operations involving different line and column spacings on the form as well as different selection of type characters or lines of type characters from the printing devices for printing on the form. The multiple column listing device 41 also provides for controlling the top and bottom margins on the sheets or forms which are printed through the use of the listing device, and the action of the top and bottom margin control means of the present listing device may be adjustably varied to conform with the desired arrangement or size of the form upon which the impressions are to be printed.

The listing device of the present invention is so constructed and arranged that when a particular adjustment or series of adjustments have been made upon the lister it is possible for the user to remove the lister as a unit from its operative association with relation to the printing machine without disturbing the adjustments which have been made in the lister, and when the lister is to again be used it may be readily returned to its operative association so as to properly perform the listing operations for which it was previously adjusted.

While the particular form and arrangement of the printing machine 40 is in many aspects of the present invention immaterial, the partic-

ular printing machine 40 which is herein shown is of the type wherein a series of individual printing devices D, Fig. 23, each bearing printing means thereon, are advanced one by one from a supply means such as an upstanding magazine M to a printing position provided in the machine. The printing position may in the present instance be considered as being defined in part by an impression means such as the platen mechanism P. The magazine M is supported on a printing machine frame 42 which in the form herein shown is generally desk-like in character so as to provide a table top T upon which sheets, forms and the like may be supported beneath the platen mechanism P for the performance of the printing operations thereon. In the operation of the printing machine 40 the printing devices D are withdrawn one by one from the bottom of the upstanding magazine M and are advanced in a step-by-step manner along a suitable feed path beneath the table top T until each printing device comes to rest at printing position. The printing position is indicated in Fig. 2 of the drawings by a dotted illustration of a printing device D located at such printing position, and it is while the printing device D is at rest at printing position that the platen mechanism P is operated to produce a printing impression from all or selected portions of the type characters embodied in the printing device. After one or more printing operations have been performed thereon or therefrom, the printing device is further advanced so as to be discharged into a collector means such as a drawer K. The form and construction of the printing machine 40 will be described herein only in so far as it is directly related to the attainment of the desired distributive listing, and for further details of the construction and operation of the printing machine 40 reference may be had to my copending application Serial No. 388,998, filed April 17, 1941.

When a printing device D is located in printing position, as shown in Fig. 2, the lines of type characters are disposed parallel to the forward edge 42' of the printing machine frame 42 with the upper or first line of such type characters located closest to the rear edge of the printing machine frame. Hence in the performance of a printing operation the form F is located with its top edge closest to the rear edge of the printing machine frame, and the location of the resulting printing impression vertically of the form F is determined by the relative vertical positioning of the form in a direction from front to rear of the printing machine frame. Similarly the location of the printing impression laterally of the form F is determined by the relative lateral positioning of the form in a direction parallel to the forward edge of the printing machine frame.

Since each printing device D remains stationary at a predetermined and fixed printing position, the desired distribution of the type characters from the printing devices to a multiple column relationship on the sheet or form F is attained through controlled shifting of the form F by the listing device 41 in timed relation to the operation of the printing machine. Thus the listing device 41 embodies a paper holder 43 to which the upper edge of the form is clamped, and the holder 43 is carried beneath a laterally shiftable lister carriage 44 for lateral movement therewith. The carriage 44 is supported for such lateral shifting or reciprocating movement by means of a lister frame 45 secured detachably to the print-

ing machine frame 42, and means is provided, as will hereinafter be explained, in association with the lister carriage 44 whereby appropriate movements are imparted to the paper holder 43 in longitudinal or vertical direction with relation to the vertical columns of the form F.

The present lister is so constructed and arranged that the lower line or group of type characters on a printing device is printed in the last printing operation pertaining to a particular printing device, and the lister is such that this last printing impression may be made in either the right-hand or left-hand column of the form F. In the embodiment shown in Figs. 1 to 24 of the drawings the lister is arranged to make the last impression in the right-hand or last column of the form, while in Fig. 25 the lister is shown in an embodiment which reverses the sequence of operation and causes the last impression, from the lower line or lines of the printing device, to be made in the left-hand or first column of the form F.

The printing devices

The printing devices D may be of many different types, and the characteristics of the printing device means must of course be related in each instance to the construction and operational characteristics of the printing machine. For use in connection with the printing machine 40 herein shown a printing device of the character disclosed, for example, in Gollwitzer Patent No. 2,132,412, patented October 11, 1938, may be employed. In other instances, where a different construction and arrangement is provided in the printing machine, a different type of printing device, such for example as the printing device shown in Gollwitzer Patent No. 1,992,661, patented February 26, 1935, may be employed. In other instances the present invention may also be utilized with printing machines which employ printing devices of the stencil type wherein a thin sheet of stencil paper is incorporated in a protective carrier or frame. In all of the various kinds of printing devices of this general class, the printing means of each printing device is arranged to embody various classes of data to be printed, and such data is disposed in a plurality of lines disposed one above another upon the operative face of the printing device so as to constitute what may be termed a single column arrangement. Such a single column disposal of the various lines of type characters is embodied in the printing device D herein illustrated, and as shown in Fig. 23 it will be evident that the several lines of type are formed upon one or more printing plates 51 which are carried on one face of a frame 50. The printing device D is, in the present instance, provided with two separately formed printing plates 51 which are removably held in position on the operative face of the printing device D by means formed on the frame 50. The lower printing plate 51 is held in position by a curled lower edge 52 and lugs 53 and 54, and a spring latch 55 serves to releasably engage a notch in one end edge of the lower printing plate 51 to hold the same in position on the frame 50. The other or upper printing plate 51 is held in place by lugs 56, 57 and 58 and a spring latch 59. Above the upper printing plate 51 a plurality of lugs 60 and a reversely bent upper edge 61 provided on the frame 50 serve to hold an index card 63 in position on the frame 50. A printing impression as at 64 may be formed on index card

63 so that the printing device may be readily identified.

The printing devices D are in many instances classified into a relatively large number of groups or classes and such classification may be attained by suitable identifying means provided at selected identifying positions on the printing device D. In the present instance the printing device D shown in Fig. 23 has a plurality of identifying tabs 65 disposed at selected positions along its upper edge in the general manner disclosed in the aforesaid Gollwitzer Patent No. 2,132,412, and in this connection it will be noted that a relatively large number of identifying positions are provided along the upper edge of the frame 50 and that the identifying means or tabs 65 in Fig. 23 are disposed in but selected ones of such identifying positions.

The data which is to be printed from each printing device is, as aforesaid, disposed upon the operative face of the printing device D in a series of lines, and when a printing device such as that shown in Fig. 23 is employed, the type characters may be formed on the printing plates 51 through the use of an embossing machine such as that shown in the patent to Duncan No. 1,518,904, patented December 9, 1924. With such a machine type characters are embossed in the metal of the printing plates 51 so that when a sheet is pressed into operative association with the embossed faces of such type characters a corresponding printing impression is made therefrom. It will be recognized, of course, that the type characters must in every instance be properly inked and this may be properly attained through inking of the type characters prior to the printing operation or through the use of an inked ribbon which is interposed between the type characters and the sheet at the time when the printing impression is made.

It will be observed in Fig. 23 that an upper line 71 of type characters is formed in the upper printing plate 51 near the upper edge thereof, but since this particular line of type characters does not enter into the example chosen to illustrate the functioning of the apparatus of the present invention, this line 67 will hereinafter be disregarded. Adjacent to the lower edge of the upper printing plate 51 a line 71 of type characters is formed, and hereinafter this line 71 will be considered as the first line of the printing device D. Beneath the first line 71, lines 72, 73, 74 and 75 of type characters are formed in succession, these lines of type characters being formed parallel to the lower edge of the printing device D. Thus as shown in Fig. 23 the printing device D has five lines of type characters formed thereon and it will be observed that sufficient space is provided along the lower edge of the lower printing plate 51 to accommodate a lower line 76 of type characters, the line 76 being indicated by a dotted line in Fig. 23 located so as to correspond with the location of the lower edges of any type characters formed in the line 76.

When a printing plate such as the printing plate 51 is formed on an embossing machine such as that hereinbefore referred to, the spacing of the lines is ordinarily uniform, but in the printing device herein shown it will be observed that the use of two separately formed printing plates 51 necessitates a non-uniform line spacing. To illustrate this difference in line spacing, dimensioning lines have been extended from the various lines of type characters in Fig. 23, these

dimensioning lines being extended from the lowermost points on each of the several lines of type. Thus the linespacing between line 71 and line 72 is indicated at 81 and this line spacing is considerably more than the line spacing between lines 72 and 73 which is indicated in Fig. 23 at 82. The line spacing between lines 73 and 74 is indicated at 83, the line spacing between lines 74 and 75 is indicated at 84 and the line spacing between the lines 75 and 76 is indicated at 85, such individual indication of the several dimensions being employed for convenience in subsequent reference to the operation of the listing mechanism of the present invention, although the line spacing indicated at 82, 83, 84 and 85 is in the present instance uniform.

The sheet or form

In the use of the apparatus of the present invention the various elements or portions of the data included in the printing means of a particular printing device may be distributed upon a sheet or form in many different relationships, and one such relationship is illustrated in Figs. 21 and 22 of the drawings. The form F shown in Figs. 21 and 22 is one in which the data embodied in the printing means of a printing device D is intended for distribution in two columns. The form F is one which is printed with suitable ruling to provide a first or left-hand column 90 and a second or right-hand column 91, and the columns 90 and 91 are each intended to receive a part of the data embodied in the printing means of each printing device D. In the present instance a binding or side border portion 93 is provided along the left-hand edge of the form F, and the division between this binding portion 93 and the first column 90 is formed by a vertical printed line 93'. The division between the first and second columns is defined by a printed vertical line 94, while the right-hand edge of the column 91 is defined by a printed vertical line 95. Other vertically arranged printed lines define a plurality of other vertically extending columns 96 which are intended and adapted to receive other and related data which may be placed therein by writing, typing or printing. The form F is also divided into a plurality of horizontal lines or areas extending horizontally across the form, that is, parallel to the upper edge 97 of the form. Thus a top marginal portion 98 is provided by a series of horizontal lines 99 printed on the form. Beneath the upper marginal portion 98 a plurality of horizontal printed lines 100 divide the form into a series of related or horizontally extending areas, and for purposes of the present description each horizontally extending area will be termed a "line" of the form F. The form also has a lower border strip or area 101 along its lower edge and this lower border area or border strip 101 serves to receive additional data which may be placed thereon as by writing, typing or printing after the performance of the distributive printing in the columns 90 and 91.

The series of related areas or lines which extend in a horizontal direction between adjacent printed lines 100 will hereinafter be referred to as lines 105 of the form F, and it will be evident that in any one line 105 in a particular column 90 or 91 it is possible to print one or more lines of type characters, as lines 71 and 72, from a printing device D. The form F shown in Fig. 21 of the drawings is intended and adapted to

receive printing impressions from two lines of type in each line 105 of the form, and because of this intended use of the form F the vertical extent or dimension of each line 105 of the form is relatively great. In other cases it may be desirable to print but a single line of type characters in each line 105 of the form, and in such an instance the printed lines 100 which define the lines 105 of the form would be more closely spaced.

It is of course desirable to locate the printed material in corresponding positions in successive lines 105 of the form, and as best shown in Fig. 22 of the drawings, it will be observed that the upper line 71' of printed characters formed in the first or upper space of each column is located in spaced relation to the upper limit of the line 105 while the lower line of type is correspondingly spaced from the lower limit of the line 105. Moreover, it will be evident that the upper line of printing in the second line 105 of the form is spaced from the upper line of printing in the upper line 105 in the form in a distance which is equal to the vertical spacing of the horizontal lines 100. This dimension is indicated at 110 in Figs. 21 and 22, and the dimension 110 may be considered to be the line spacing of the particular form F.

Such dimensioning of the form F in Figs. 21 and 22 is indicated in the present instance through the extension of dimensioning lines from the lower edges of the upper lines of type printed in the successive lines of the form, and this mode of dimensioning will be followed throughout the present description so that in each instance the point of reference employed as to a line of type characters will be the lower limit or base of such characters. The location of the uppermost printing impression in each form F must of course correspond with the printed division lines provided on the form F, and the distance of the upper line of printing on each form from the upper edge 97 of the form may be termed the top margin of the form. The dimension of this top margin is indicated in Fig. 21 of the drawings at 111. The bottom margin of the form F is also indicated in Fig. 21 at 112, this bottom dimension being shown as extending from the lower edge 113 of the form F to the lower edge of the upper line of type which is to be printed in the lower line 105 of the form. This mode of dimensioning is adopted by reason of the fact that the form F shown in Fig. 21 is designed for the printing of two lines of type characters in each of the lines 105, and by so indicating the extent of the bottom margin the description is rendered generic to forms for either one or more lines of type characters in each line 105 of the form.

The first letter or character printed in each of the columns 90 and 91 should of course be spaced in a predetermined relation to the left-hand border edge of the column in which it is printed, and in most instances the distance between the first character in the column 91 would be equal to the distance between the division lines 93 and 94. However, since the character of the work may in some instances call for a different location of printing in the two columns, the distance between the first characters printed in the two columns has been indicated at 115 as being the column spacing dimension of the form F.

The printing machine

The printing machine herein illustrated is of the type wherein the impression means is pro-

vided by the platen mechanism P, and this platen mechanism is supported in an operative relationship above the table top T by means of a printing frame 125, the specific construction of which is illustrated and described in my copending application Serial No. 350,678, filed August 3, 1940, now Patent No. 2,275,439, patented March 10, 1942. The printing frame 125 is in the present case disposed so as to project upwardly from the table top T at a point located a considerable distance rearwardly and to the right of the printing position, and the printing frame extends forwardly at an angle of substantially 45° with respect to the forward edge 42' of the printing machine frame, thereby to locate the forward end of the printing frame 125 directly above the printing position. The magazine M is located just to the right of the vertically extending portion of the printing frame 125 and the printing devices D are advanced from the bottom of the magazine M in a forward direction and then along a suitable guide path beneath the table top T and to printing position. The particular arrangement and construction of the printing device advancing path is disclosed in my aforesaid copending application Serial No. 388,998. The printing device advancing means of the printing machine is arranged to advance the printing devices in a step-by-step manner such that each printing device comes to rest at a plurality of different stations along the printing device guideway, and in the machine herein disclosed the first of these stations constitutes a sensing station at which suitable identifying means such as the tabs 65 may be sensed to determine whether or not each printing device carries such a tab at one or more selected identifying positions thereon. The sensed presence or absence of selected identifying means on the printing device when the printing device is at sensing station may be rendered operative to control the operation of the platen mechanism P when the printing device from which the sensed indication is derived reaches printing position. The selector mechanism whereby such controlling action is attained is but fragmentally shown in the present drawings wherein a control plunger 126 is shown on the front panel of the machine frame for rendering the selector mechanism active or inactive as desired. Further details of the construction and operation of the selector mechanism may be had by reference to my copending application Serial No. 392,151, filed May 6, 1941. The platen mechanism P is herein illustrated as being of the form which is incorporated in the printing machine shown in my copending applications, Serial No. 350,678 and Serial No. 388,998, and this platen mechanism is described in detail in my copending application, Serial No. 361,530, filed October 17, 1940. The platen mechanism P comprises a carriage C supported for reciprocation in a direction from front to rear of the printing machine along a guideway provided beneath a head 130 mounted beneath the forward end of the printing frame 125, and a platen roller PR is supported on and carried by the carriage C. The platen roller PR is arranged in a horizontal position at right angles to the path of reciprocation of the carriage C, that is, parallel to the forward edge 42' of the printing machine frame. The platen roller PR is supported by means such as toggles so that the platen roller may be shifted from a normal elevated or inactive position to a lower or active position wherein the platen roller may be effec-

tive to press a sheet or form such as the form F into printing cooperation with a printing device disposed at printing position. The platen mechanism P in the form herein disclosed is arranged so that the platen roller is in its elevated or inactive position when the carriage C is at its rearward or at rest position shown in Fig. 1 of the drawings. When a printing operation is to be performed the carriage C is actuated in a forward direction through an idle stroke by means of actuating mechanism indicated generally at 131 in Fig. 1 of the drawings, and in the course of such forward movement of the carriage C the toggle means are actuated to shift the platen roller PR to its lower or active position. The platen roller PR reaches its lower or active position at substantially the time when the forward stroke of the carriage C has been completed and the toggle means is then latched so as to maintain the platen roller in its lower or active position during the return or rearward stroke of the carriage C. Hence during the rearward or active stroke of the carriage C the platen roller PR may be rolled across the sheet to effect the desired printing operation. As the platen roller approaches the rear end of its stroke and has completed the desired printing operation, it is withdrawn to its elevated or inactive position so that the sheet or form may be readily shifted, or removed and replaced by a new sheet.

In the normal use of a printing machine such as the printing machine 40 the various operative cycles of the printing machine are normally initiated by selective manipulation of control means such as a plurality of foot pedals 140, 141 and 142, Figs. 1 and 20, which are disposed near the floor beneath the frame 42. The pedals 140, 141 and 142 are disposed in or adjacent to the knee-hole opening of the desk-like frame 42 so as to be located for convenient manipulation by an operator seated immediately in front of the adjacent edge of the printing machine frame. The foot pedals 140, 141 and 142 are rendered active by momentary depression thereof, and when thus actuated may serve selectively to initiate different types of single cycle operations of the actuating means which are embodied in the printing machine. These actuating means are fully described in my aforesaid copending application Serial No. 388,998, and reference may be had to this copending application for details of construction and operation of the actuating and control means of the printing machine 40.

For purposes of disclosure of the present invention it is sufficient to point out that the printing machine 40 has a driving motor 145, Figs. 20 and 26, which as shown in Fig. 26 is energized through a switch 146 controlled by a control plunger 147 located in the forward panel of the printing machine as shown in Fig. 1. The motor 145 serves through suitable speed reducing means including a pair of belts 148 to constantly drive a pulley 150, this pulley being mounted on a main drive shaft 151, Figs. 16, 17 and 18, which is normally stationary in a rotative sense and is rotated through a single revolution each time the printing machine is to be operated through an active cycle of any kind. Support for the drive shaft 151 is provided by a plurality of bearing brackets 152 carried on a mounting rail 153 which, as shown in Figs. 2 and 20, extends parallel to the rear edge of the machine and relatively close to the table top T. The shaft 151 is located in a horizontal position just forwardly of and

slightly below the mounting rail 153. As hereinbefore pointed out the pulley 150 is constantly driven and runs loosely or freely on the shaft 153. The drive means or drive paths from the shaft 151 to the various operative mechanisms of the printing machine are arranged for connection to the drive shaft 151 and the drive pulley 150 in a selective manner as the several mechanisms are to be operated. For this purpose a plurality of clutches are provided on the shaft 151, one of these clutches (not herein shown) serving to connect the shaft 151 to the pulley 150 and the other two of these clutches which are herein indicated generally at 155 and 156 in Fig. 20 serve to selectively connect operative mechanisms of the machine to the drive shaft 151. All of these clutches are generally similar in form and construction, the first one of the clutches which serves to connect the driving pulley 150 to the drive shaft 151 being termed the master clutch, while the clutches 155 and 156 are respectively termed the printing device advancing clutch and the platen clutch. These clutches are of the one-revolution type and are fully described in my aforesaid copending application Serial No. 388,998. For present purposes it is sufficient to point out that the advancing clutch 155 is controlled in a primary sense by a stop lever 155' which may be shifted to a released position through a linkage 157 which is connected to the foot pedal 140. The advancing clutch 155 is operative when it is thus released to assume an engaged relation wherein it serves to operate the printing device advancing means of the printing machine through an operative advancing cycle. The other one of the clutches, that is, the platen clutch 156, is controlled in a primary sense by a stop lever 156' which may be actuated to a released position through a linkage 158 connected to the foot pedal 141. As described in my aforesaid copending application Serial No. 388,998, the release of either one of the stop levers 155' or 156' serves through means including a stop lever 159, Fig. 20, to release the master clutch and thereby cause rotation of the drive shaft 151 through a one-revolution cycle.

Since the foot pedal 140 serves only to cause engagement of the advancing clutch 155 and to thereby cause a printing device D to be advanced through printing position without the performance of a printing operation, this foot pedal 140 is often termed the skip pedal of the machine. The foot pedal 141 serves to cause operation of the platen mechanism only, and for this reason the foot pedal 141 is often termed the repeat pedal. It will be understood that the actuation of the various foot pedals is momentary in character, since it is desirable to permit the stop levers to return to their active positions in time to terminate the operation of the machine at the end of one cycle.

The foot pedal 142 is arranged, when momentarily depressed, to cause simultaneous or timed operation of the printing device advancing means and of the platen mechanism P, and, since such operation results in the performance of but a single printing impression from each printing device, the foot pedal 142 is often termed the consecutive pedal of the printing machine. The term "consecutive" as applied to the foot pedal 142 is, however, merely a term of convenience since the printing machine 40 as disclosed in my aforesaid copending application Serial No. 388,998

shown this switch is governed by a detecting finger 189. The detecting finger 189 as disclosed in detail in my aforesaid copending application Serial No. 388,998, is arranged as a detecting means associated with the magazine M and in each cycle of operation of the machine the finger 189 moves into contact with the lower printing device to detect the withdrawal of the last printing device from the magazine M. Hence when the last printing device is withdrawn from the magazine M the detecting finger 189 moves through an additional stroke to the left so as to engage one blade of the normally open switch 187 and thereby close this switch. The conditioning switch 185 is so arranged that it is controlled by the auto-stop plunger 180 and the control is such that the switch 185 is closed when the printing machine is operated continuously under control of the auto-stop means, and hence when the switch 187 is closed by the detecting finger 189, the solenoid 181 is energized and the auto-stop plunger 180 is actuated to its innermost position so as to cause continuous operation of the machine to be stopped.

As hereinbefore pointed out the continuous operation of the printing machine under control of the auto-stop means may be modified in many instances through the dominating action of the selector mechanism, as disclosed in detail in my copending application Serial No. 392,151. When the selector mechanism is operative there will of course be certain cycles of operation of the printing machine wherein the platen mechanism P will remain inactive, so that while the printing machine will maintain its continuous operation under control of the auto-stop means, certain printing devices D will be skipped.

The foregoing relationship of the auto-stop means to the operation of the printing machine is utilized, as will be hereinafter described in detail, to cause automatic stopping of the printing machine when the printing of a form has been completed by the multiple column lyster 41.

The multiple column lyster

As hereinbefore pointed out, the multiple column lyster of the present invention is adapted for distribution of the printed matter from each printing device into a plurality of different columns, and in accordance with the particular construction of the multiple column lyster this distribution may be in two or more columns. For purposes of disclosure the embodiment of the invention for the attainment of two column listing will first be described, this form of the lyster being shown in Figs. 1 to 26 of the drawings. In attaining the desired distribution of the printed matter upon the form F, the paper holder 43 is shifted in two different directions, the first one of which is attained through lateral shifting movement of the lyster carriage 44 parallel to the front edge 42' of the printing machine, and the other of which is attained through movement of the paper holder 43 relative to the lyster carriage 44 in a direction at right angles to the path of shifting movement of the lyster carriage. The shifting movement which is attained through actuation of the carriage 44 will hereinafter be termed the transverse shifting movement, and it is through such manipulation of the paper holder 43 that the different columns of the form F, such as the two columns 90 and 91 are successively brought into the desired operative relation to the printing position. The lateral or transverse shifting movement of the lyster

carriage 44 is attained through a cam mechanism designated generally as 200 in Fig. 2 of the drawings, this cam mechanism acting through a lever 201 and a connecting link 202 to appropriately actuate the lyster carriage 44.

As a preliminary to detailed description of the multiple column lyster 41 it may be observed that after selected lines of type characters such as the lines 71 and 72, Figs. 21 to 23, have been printed 10 in the column 90 to form printing impressions 71' and 72', the form F, in addition to its lateral shifting movement to align the column 91 with the printing device D, must also be shifted in a downward direction so that the printing impression 71' will be aligned with the upper one of 15 the lines of printing characters on the printing device which is to be printed in the column 91. The amount of such reverse or back spacing movement of the form F may vary in accordance 20 with the line spacing employed on the printing device D and may also vary in accordance with the particular line or lines selected for printing in the column 91. In the example herein shown the line 75 has been selected for printing 25 in the second column or the column 91 and hence the reverse shifting movement of the form F must be through a distance which is equal to the distance between the lines 71 and 75 on the printing device. This distance is indicated by the 30 dimensioning line 204 in Fig. 23 of the drawings.

After the second printing operation, which forms an impression 75' from the line 75 in the appropriate space in the column 91, the paper holder 43 is again shifted laterally so as to bring 35 the first column or column 90 into alignment with the printing position, the printing machine being operable before the performance of the next printing operation to feed another printing device D to printing position. In addition to the 40 aforesaid lateral shifting movement of the form F, the form must also be advanced so as to bring the next line 105 of the form into the proper vertical relation to printing position, and such advancing movement or line spacing movement 45 of the carriage of the paper holder 43 involves two increments of movement, the first of which corresponds with the line spacing 110 of the form F and the other of which corresponds with the back spacing which was imparted to the form. 50 F in connection with the previous printing operation. In other words, the line spacing advancing movement of the paper holder F is equal to the sum of the line spacing dimension 110 and the back spacing dimension 204.

55 The frame 45 of the multiple column lyster 41 is provided by two generally U-shaped side frame members 205, the lower arms 206 of which have mounting feet 207 formed thereon whereby the frame 45 may be operatively supported on the 60 rear wall 208 of the printing machine frame, as shown in Fig. 3 of the drawings. The U-shaped formation of the frame members 205 provides a throat about the projecting rear edge of the table top T, and also provides clearance space into 65 which the paper holder 43 may be moved when exceptionally long forms F are being printed. The U-shaped form of the side frame members 205 also provides a generally horizontal upper arm 207 projecting forwardly over the table top T for a substantial distance, and in addition, a rearwardly projecting arm 207' is provided on each side frame member. The side frame members 205 are connected together by cross bars or rails 210, 211 and 212 which serve to hold the 70 two side frame members 205 in a rigid relation. 75

ship, such that working space is provided therebetween for mounting and movement of other operative parts of the lister. The cross bars 210 and 212 also serve to provide a trackway upon which the lister carriage 44 is supported and guided for its transverse reciprocating movement. Thus the cross bar 212 is located adjacent to the forward ends of the side frame members 205, and the rear edge of the cross bar 212 is tapered or pointed at 212' for engagement by a pair of grooved rollers 213. The grooved rollers 213 are supported by a pair of spaced studs which project upwardly from the top of the lister carriage 44, and the two rollers 213 are held in engagement with the tapered edge 212' by a generally similar roller 215 mounted on the lister carriage 44 so as to engage the forward edge of the rail 212.

The lister carriage 44 is provided with a downwardly extending bracket 217, Figs. 3, 6, 7 and 8, located just rearwardly of the throat which is provided in the side frames 205, and the rail 210 has a tapered upward edge 210' which is engaged by a pair of laterally spaced grooved rollers 218 mounted just forwardly of and upon the mounting bracket 217. The two spaced rollers 218 are held in engagement with the upper edge 210' of the rail 210 by a lower roller 219 carried on the mounting bracket 217 and engaging the lower edge surface of the rail 210. The mounting bracket 217 also provides a downward extension or stud 220 to which one end of the link 202 is pivoted as shown in Figs. 3, 7 and 8. Since the rollers 218 and 219 are mounted on horizontal axes and are spaced a considerable distance rearwardly from the rail 212, it will be evident the lister carriage 44 is guided accurately along a rectilinear path which may be accurately adjusted with relation to the printing position of the machine to thereby attain accurate positioning of the printing impressions on the form F.

In attaining such accurate location of the guideway provided by the rails 210 and 212 and the associated supporting and guiding rollers, means is provided on the two side frame members 205 whereby the operative association of the lister 41 with the printing machine 40 may be adjustably varied to meet the conditions encountered in various printing machines. Thus each mounting foot 207 has a headed stud 225 mounted therein adjacent to the upper limit of the mounting foot 207, the headed mounting stud 225 being threaded into the mounting foot as indicated at 226 and having a lock nut 227 thereon whereby the extent of projection of the head of the stud 225 may be adjusted by manipulation of the stud itself, and the stud may be secured in adjusted position by tightening of the lock nut. In the mounting of the lister 41 on a printing machine 40 the heads of the studs 225 are inserted into suitable keyhole slots 228 formed in the back panel 208 of the printing machine frame and are shifted laterally in the keyhole slots so as to engage the narrow portions thereof and thereby prevent endwise withdrawal of the studs 225. When the headed studs 225 are thus engaged with the keyhole slots 228, the lower portions of the mounting feed engage with a mounting bar 230 which is secured on the outer or rear face of the rear wall 208. Each mounting foot 207 has a downwardly and forwardly facing rabbeted groove 231 which engages the upper rear corner of the mounting bar 230 to transmit the weight of the lister 41 principally to the bar 230. When the lister has been shifted laterally to engage the headed studs 225 with the small ends of the key-

hole slots 228, a securing bolt 232 on each of the mounting feet 207 is aligned with an appropriately located screw-threaded aperture 233 formed in the proper position in the mounting bar 230. By means of a projecting head 234 the two securing bolts 232 are screwed in the apertures 233 to thereby secure the lister 41 in position on the printing machine. In addition, the endwise positioning of the headed studs 225 with relation to the rear wall 208 is maintained by knurled lock nuts 235 which are provided on each of the studs 225 so that they may be screwed into firm engagement with the outer or rear face of the rear wall 208.

As hereinbefore pointed out, it is desirable to have the transverse path of the paper holder 43, and hence of the lister carriage 44, parallel to the forward edge 42' of the printing machine so that when the paper holder 43 is moved from front to rear the several printing impressions formed in each column will be parallel to the lines of the form which define the side edges of the columns thereof. Such adjustment is attained in part by adjustment of the headed studs 225, these studs being screwed inwardly or outwardly of the threaded openings 228 to effect such positioning. In addition to such adjustment, the manner of engagement of the rabbeted grooves 231 with the rear face of the mounting bar 230 may be adjusted by means of adjusting screws 236 having lock nuts 237 thereon, these adjusting screws 236 being located in the mounting foot 207 just above and just below each of the securing bolts 232, as will be evident in Figs. 3 and 8 of the drawings.

A lister carriage 44 as herein shown is formed from an elongated sheet metal plate having downturned edge flanges 240 along its side and rear edges as will be evident in Figs. 1 and 3, and means is provided on the lower face of the sheet metal plate for supporting the paper holder 43 for the desired longitudinal shifting movement. In accordance with the present invention such support for the paper holder 43 is provided through an intermediate carrier 250 which in the present instance is in the form of an elongated bar of an inverted U-shaped or channel-like form, as will be evident in Fig. 5 of the drawings. The carrier 250 serves a variety of functions in that it provides a longitudinal guideway along which the paper holder 43 may be shifted longitudinally to effect the desired line spacing thereof, and it also provides a carrier through which rearward or back spacing movement is imparted to the upper carrier. Such back spacing movement is, of course, of a limited extent, and to effect such back spacing movement the carrier 250 must move through but a relatively limited distance. Means is therefore provided to act between the carrier 250 and the lister carriage 44 to support and guide the carrier 250 for such limited movement. To this end a pair of supporting and guiding plates or strips 252 are mounted on the lower surface of the lister carriage 44 by means of rivets 253 and spacers 254, the two supporting and guiding strips 252 being spaced from each other on opposite sides of the center line of the carriage 44 and providing extending edge portions 255 which are parallel to each other and are adapted to be engaged by complementary guide means provided on the carrier 250. In the present instance this guide means comprises a plurality of transverse bars 256 which are secured by means such as rivets 257 so as to extend laterally across the top of the carrier bar 250 at spaced points there-

along. The supporting bars 258 have notches or grooves 258 in their opposite ends which engage with the edge portions 255 of the supporting strips 252 to slidably support and guide the carrier bar 250 for a limited reciprocating movement longitudinally of the lister carriage 44.

The carrier bar 250 has its flanges 260 arranged to extend downwardly, and these flanges are provided with guiding means whereby the paper holder 43 is supported and guided for longitudinal movement along the carrier bar 250. This means in the present instance comprises a longitudinal outwardly facing groove 261 formed in each of the flanges 260, and the paper holder 43 has a pair of flanged plates 262 secured thereto so that the adjacent edges of these plates extend into the longitudinal grooves 261 to thereby support and guide the paper holder for sliding movement longitudinally along the carrier bar 250.

The paper holder 43 is illustrated in detail in Figs. 12 to 15 of the drawings wherein it will be evident that the paper holder includes a cross bar 270 upon the top of which the two plates 262 are secured in a rigid relationship by means such as rivets 271. Since the flange plates 262 are relatively long, as will be evident in Fig. 4 of the drawings, a bracing plate 272 is preferably provided so as to extend between the two flange plates 262 somewhat rearwardly of the cross bar 270 of the paper holder. The bracing plate 272 is secured to the flange plates 262 by rivets 273. The cross bar 270 is formed from sheet metal and as shown in detail in Fig. 15 a downwardly extending rear flange 274 is provided and at the lower end of the flange 274 a forwardly extending horizontal flange 275 is provided. The ends of the cross bar 273 are bent downwardly to provide end flanges 276, and a pair of shafts 277 and 278 are mounted in the flanges 276 so as to extend longitudinally of the cross bar 270 and in spaced parallel relation to each other. An intermediate support is provided for the shaft 278 by a downturned lug 279 which is struck from the body of the cross bar 270. The forward one of the two shafts, that is, the shaft 278, constitutes a mounting shaft upon which a pair of paper clamps 280 are mounted, while the rear shaft 277 constitutes an operating shaft whereby the clamps 280 may be actuated between open and closed positions. Each clamp 280 comprises a lower member 281 and an upper member 282, both of which are formed from sheet metal to provide hinge loops which embrace the mounting shaft 278. The lower clamp member 281 has hinge loops 283 thereon while the upper clamp member 282 has hinge loops 284. The two clamp members 281 and 282 extend forwardly from the mounting shaft 278 to provide a lower jaw 281' and an upper jaw 282' which are adapted to be separated for the insertion of the upper edge of a sheet or form therebetween. A rubber cushioning member is preferably provided on the lower surface of the upper clamping jaw 282' as indicated at 285 in Fig. 15. To facilitate the insertion of a sheet of paper into the space between the two clamping members, the forward end of the lower clamping jaw is bent downwardly as at 286 to provide a guiding surface along which the edge of a piece of paper may be shifted to a position between the two opposed jaws. Such inserting movement is limited by means of a pair of upstanding lugs 287 which are struck from the material of the lower clamp member 281 so as to extend upwardly through slots 287' formed in the upper

clamp member. Proper positioning of the form F in a lateral sense is facilitated by a side guide 288 which is secured to the mounting rail 42", Fig. 1, so as to extend along the table top T in position to be engaged by one edge of the form during a loading operation.

The lower clamp member 281 has a rear end portion 289 which overlies the flange 275 of the cross bar, while the upper clamp member 282 has a rearwardly extending arm 290 which underlies the actuating shaft 277. An expansive coil spring 291 positioned between the two arms 289 and 290 serves to urge these two arms apart, thereby to urge the clamping jaws 281' and 282' into clamping relationship. When an operator wishes to release the paper clamps 280, the rear end of the upper arm 290 is urged downwardly against the force of the spring 291, and this end is attained by cam means. Such cam means in the present instance is provided by flattened surfaces 292 formed on the actuating shaft 277. These flattened surfaces 292 extend for a considerable distance along the bottom of the actuating shaft 277, thereby to permit the two paper clamps 280 to be shifted along their supporting shaft 278 while maintaining the desired operative relationship between the paper clamps and the actuating shaft 277. For the purpose of operating the actuated shaft 277, an actuating knob 295 is fixed on the projecting left-hand end of the actuating shaft 277. The actuating knob 295 has arms 296 and 297 projecting radially therefrom at circumferentially spaced points, and when the actuating knob 295 is in the position shown in Fig. 14 the actuating shaft is in the position shown in Fig. 15 and the clamps 280 are in their clamping position. When an operator wishes to release the paper clamps 280, the actuating knob 295 is rotated in a counterclockwise direction from the position shown in Fig. 14 until the arm 296 engages a stop pin 298 which projects from the left-hand flange 276. This movement is sufficient to rock the shaft 277 to a point where it will maintain its position and will maintain the clamps 280 in their open relationship. When an operator has reloaded the paper holder by placing a sheet between the two clamps 280, the clamps are released for movement to their clamping position by merely rocking the actuating knob 295 in a clockwise direction toward a position shown in Fig. 14. In order that the desired relation of the paper holder 43 to the table top may be maintained at all times despite the rapid shifting of the paper holder, a pair of snubber devices 299 is provided near opposite ends of the cross bar 270. As shown in Figs. 12 and 13, each snubber device 299 comprises a spring arm 300 secured at one end as by rivets 301 to the lower surface of the cross arm 270, and on its other or forward end each spring arm 300 carries a downwardly projecting boss 302 which has a rounded lower end riding on the table top T. Thus the snubbers 299 act to stabilize the paper holder 43 in its various movements, and prevent interfering contact of the sharp edged parts of the paper holder with the table top.

Advancing or line spacing movement is imparted to the paper holder 43 by means which extends rearwardly from the paper holder along the carrier 250, and as herein shown this means comprises a flexible rack 310 which is shown in detail in Fig. 24 of the drawings. The flexible rack 310 has an opening 311 at its forward end, and to connect the flexible rack 310 to the paper

holder 43 the opening 311 is placed in position upon an upstanding screw-threaded stud 312 which is mounted on the cross bar 270 between the forward ends of the supporting flange plates 262. A nut 313 is placed on the upper end of the stud 312 and is tightened upon the flexible rack 310 to hold the same in the desired relationship to the paper holder 43. For purposes which will hereinafter appear, the opening 311 is made in the form of a slot extending longitudinally of the flexible rack, thereby to enable the flexible rack 310 to be associated with the paper holder in different adjusted relationships. The flexible rack 310 extends rearwardly between the two flanges 260 of the carrier 250, and since the flexible rack is made from a relatively flexible spring steel strip which is in a sense incapable of supporting itself in a predetermined relationship, the inner faces of the flanges 260 are provided with longitudinal slots 315 into which the opposite edges of the flexible rack extend. A slot 316 is formed in the lower edges of each of the flanges 260 near the rear end of the carrier 250, thereby to provide for a downward bending of the rear end of the flexible rack 310, as shown in Fig. 6 of the drawings. As the flexible rack 310 is actuated in a rearward direction for the purpose of imparting advancing or line spacing movement to the paper holder 43, the rear end of the rack is maintained in an out of the way relationship within a coiling receptacle 317. The coiling receptacle 317 is mounted upon a vertical mounting plate 318 which is secured to and depends downwardly from one side edge of the carrier bar 250. The cylindrical coiling receptacle 317 is open on both of its sides, as indicated by the opening 318' in Fig. 6, on its other open side the receptacle has an inturned flange to maintain the flexible rack in position laterally within the coiling receptacle 317. The coiling receptacle 317 has a top opening 319 in register with the slots 316 so that the end of the flexible rack may be entered into the receptacle 317.

The flexible rack 310 is provided with a plurality of openings 320 which are arranged in spaced relation to each other longitudinally of the rack 310. These openings 320 are disposed in two longitudinally extending rows spaced laterally of the flexible rack and the openings 320 are disposed alternately in the two rows. The openings 320 are utilized as will hereinafter be described in imparting longitudinal advancing movement to the flexible rack 310 and hence to the paper holder 43.

When a line spacing movement is to be imparted to the paper holder 43 the flexible rack 310 is engaged and the paper holder is moved longitudinally in a paper-advancing direction along the carrier bar 250, and after a printing impression has been made from one or more of the upper lines of type of a printing device, the paper holder is back spaced in an amount sufficient to align the impression which has just been made with the selected one or more of the lower lines of type from which the second impression is to be made. Such back spacing movement is imparted to the paper holder 43 by a back spacing movement of the carrier 250, the paper holder 43 at this time being held frictionally in a stationary relationship with respect to the carrier bar 250 and the carrier bar being shifted through the requisite back spacing stroke. The back spacing carrier 250 must then be returned in an advancing direction so as to be conditioned for its next back spacing movement, and such con-

ditioning movement is imparted to the back spacing carrier 250 during the time when the line spacing advancing movement is being imparted to the paper holder 43.

The movements which are required as aforesaid in the line spacing and back spacing of the paper carrier are, in accordance with the present invention, obtained through the use of means which operate as an incident to the transverse shifting movement of the lister carriage 44. These means are located above the lister carriage 44 and are mounted on the lister frame in such a location as to be readily accessible for adjustment or inspection. These actuating means, in accordance with the present invention, comprise a pair of independently adjustable cam devices, one of which is operable in the course of transverse movement of the lister carriage 44 in one direction to impart the desired line spacing movement to the paper holder 43, while the other of the two cam devices is operable in the course of movement of the lister carriage 44 in the opposite direction to impart the requisite back spacing movement to the paper holder 43. These cam devices are, in accordance with the present invention, so constructed and arranged that the line spacing and the back spacing movements imparted to the paper holder may be varied, and in addition these cam devices are of such a character as to permit variation of the line spacing to be attained easily and conveniently in the use of the lister. In other words, the line spacing means and the back spacing means of the present lister are in a sense independent of the column spacing, and hence any desired line spacing or back spacing may be attained, within reasonable limits, even though changes are also made in the column spacing. The cam devices are normally concealed beneath a cover 335 which rests on the upper edges of the arms 207 and 207' of the side frames 205, and the cover 335 is held removably in place by screw devices 336 which extend through the cover 335 and are threaded into the side frames 205. Hence upon removal of the cover 335 the cam devices are exposed for inspection or adjustment.

In the present instance the line spacing movement is attained through an elongated cam 350 while the back spacing movement is attained through the action of an elongated cam 351. The two cams are mounted on the frame 45 so as to overlie the carriage 44, a base plate 352 being secured by screws 353 upon the top of the cross rail 211 near one end thereof while an adjusting plate 354 is mounted by screws 355 on the top of the cross rail 211 adjacent to the other end of the rail 211. In the embodiment shown in Figs. 1 to 20 the mounting or base plate 352 is located near the right end of the rail 211. The two plates 352 and 354 both extend in opposite directions from the rail 211, and the cam 350 is pivotally mounted at one of its ends by a pivot pin 356 upon the rearwardly projecting end of the mounting plate 352. The corresponding end of the back spacing cam 351 is pivoted by a pin 357 on the forwardly projecting end of the plate 352. The other ends of the two cams 350 and 351 are operatively connected to the adjusting plate 354, and their connection is such that the two cams may be independently adjusted in a horizontal plane so that each cam may be disposed at different angles with respect to the path of reciprocation of the lister carriage 44. Thus the rearwardly projecting end of the 75 adjusting plate 354 has an elongated arcuate

slot 358 formed therein centered upon the pivot pin 356, and a screw and nut device 359 extends through the slot 358 and the adjacent end of the cam 350 so that this end of the cam 350 may be secured in any adjusted position along the slot 358. The forwardly projecting end of the adjusting plate 354 has a similar elongated arcuate slot 360 formed therein centered on the pivot pin 357, and a screw and nut device 361 extends through the slot 360 and the adjacent end of the cam 351 so that this end of the cam may be secured in any adjusted position along the slot 360. Thus the angularities of the cams 350 and 351 with respect to the path of reciprocation of the lister carriage 44 may be independently adjusted.

The forward one of the cams, that is, the cam 351, is utilized to impart the desired back spacing movement to the carrier bar 250, and for this purpose a longitudinal cam slot 371 is provided in the cam 351 for engagement with a cam roller 372 mounted on the carrier bar 250. As shown in Figs. 2 and 3, the cam roller 372 is mounted on an upstanding bracket 373 of an inverted U-shaped form, this bracket 373 being secured upon the upper face of the carrier bar 250 so as to project through a longitudinal slot 374 formed in the top of the lister carriage 44. For purposes which will hereinafter appear, the cam roller 372 is carried on a stud 376 which is adjustable along the top of the bracket 373 in a longitudinal slot formed in the bracket 373. Thus, it will be evident that when the lister carriage 44 is shifted transversely back and forth by the cam mechanism 200, the roller 373 will ride in the cam slot 371, and in accordance with the adjusted angularity of the cam slot 371 and the length of the stroke of the lister carriage 44, the carrier bar 250 will be shifted through a predetermined longitudinal reciprocating stroke.

The other or line spacing cam 350 acts to impart the desired line spacing or advancing movement to the flexible rack 310 through the medium of a line spacing slide 380 mounted on the lister carriage 43 for reciprocating movement longitudinally of the carriage within the slot 374, the line spacing slide 380 being provided with one-way driving means arranged to engage rack 310 to shift the same in a rearward or line spacing direction. The line spacing slide 380, as shown in Figs. 3, 6 and 11 is, in effect, hollow and has transverse cross bars 381, Fig. 4, across its bottom face which are slotted at their ends so as to engage and ride along the guide flanges 255 of the lister carriage. Thus the line spacing slide 380 is slidably supported and may be reciprocated along the carriage 43, parallel to but independently of the reciprocating movement of the carrier bar 250. Such reciprocating movement of the line spacing slide 380 is attained by a cam slot 381 formed longitudinally in the cam plate 350 and engaged by a cam roller 382 mounted upon a stud 383 projecting upwardly from the top of the slide 380.

Thus, the line spacing slide 380 is reciprocated in a longitudinal direction with relation to the carrier bar 250 and the length of such reciprocating stroke varies in accordance with the adjusted degree of angularity of the cam slot 381 and the length of the transverse or column spacing stroke of the lister carriage 44. Within the hollow line spacing slide a pair of pawls 385, Fig. 6, are pivoted on a common pivot pin 386, and rearwardly of the pivot each pawl 385 has a downwardly projecting rearwardly facing

tooth 387. The teeth 387 are arranged to extend downwardly between the cross bars 381 and through a slot 388 formed in the top of the carrier bar 250, thereby to bear normally upon the top of the flexible rack 310. The pawls 385 are so disposed laterally that the tooth 387 on the left-hand pawl is adapted to engage any one of the left-hand row of openings 320 in the flexible rack 310, while the other pawl bears a similar relationship to the right-hand row of openings 320, and the pawls are urged toward such engagement by springs 389, Fig. 6, acting between the top wall of the slide 380 and the tops of the pawls. If desired, either or both of the pawls 385 may be raised to inactive position by means of projecting rear end portions 385' which extend beyond the rear end of the slide 380.

Since the operative stroke of the line spacing slide 380 is in a rearward direction, and the effective stroke of the back spacing carrier 250 is in a forward direction, it is the rearwardly facing edge surface 381' of the cam slot 381 and the forwardly facing edge surface 371' of the cam slot 371 which effect such operative strokes, and for this reason the cam rollers 372 and 382 are preferably maintained in engagement with the surfaces 371' and 381' respectively by means of a spring 382' which is connected between the tops of the two studs 376 and 383.

The reciprocating stroke of the line spacing slide 380 is arranged, by appropriate adjustment of the angularity of the cam 350, to be somewhat more than the amount of advancing or rearward movement which is to be imparted to the flexible rack 310. Hence, in each line spacing or rearward stroke of the slide 380, the active faces of the teeth 381 will terminate their movement at a particular point, and opening 320 which has been engaged by a tooth 387 will be moved to what may be termed a particular reference point with respect to the lister carriage. Therefore, in order to attain the desired line spacing of the paper holder 43 the openings 320 in the rack 310 are spaced from each other in a longitudinal direction in an amount indicated as 110R which corresponds with the line spacing dimension 110 of the form F. Since the racks 310 are readily replaceable, the line spacing dimension may of course be readily changed; and in this connection it may be observed that a rack 310 having a particular spacing 110R may be employed for attaining any line spacing 110 which is a multiple of the spacing 110R.

As a line spacing advancing movement is imparted to the paper holder 43, it will be recalled that the carrier bar 250 is concurrently shifted in a rearward direction through a conditioning movement, and although such conditioning movement of the carrier bar 250 progresses somewhat slower than the line spacing movement of the slide 380, it will nevertheless be apparent that at least a portion of the rearward movement of the paper holder 43 (and the rack 310) will be the result of such conditioning movement of the carrier bar 250. When the lister carriage has reached the left-hand position, Fig. 2, so that the line spacing movement of the paper holder has been completed, the printing machine 40 is near the midpoint of its operating cycle and soon thereafter the platen face PF which is adapted for selective printing of the first line or group of characters from the printing device D is brought into operative association with the then sta-

tionary form F to thereby make printing impressions, as 71' and 72', in the column 90.

In the first half of the next cycle of operation of the printing machine 40 the back spacing carrier bar 250 imparts the requisite back spacing movement to the paper holder 43 as the lister carriage 44 is moved to its right-hand position of Fig. 2, and this movement is completed in ample time for the appropriate platen face PF to enter into printing cooperation with the form F to thereby produce a printing impression, as 75', in the proper aligned relation in the corresponding line 105 of column 91. As the back spacing movement of the carrier bar 250 progresses it will be evident that the return or forward movement of the line spacing slide 380 progresses even more rapidly, and in such relative movement the pawls 385 are cammed upwardly out of the openings 320, as required, by sloping forward faces 387 on the teeth 387. Near the end of the back spacing operation the teeth 387 cam upwardly over an edge 390 of a shield 391 so as to come to rest in disabled positions such that the pawls 385 cannot exert a restraining action of any kind upon the rack 310 or the paper holder 43 so long as the pawls 385 are thus disabled. The shield 391 is formed from a thin strip of material such as spring steel and is mounted in the grooves 315, Fig. 5, so that the shield 391 formed in the inner faces overlies the flexible rack 310. Thus the shield 391 is in effect interposed between the rack 310 and the pawls 385. The shield 391 is inserted into the grooves 315 from the rear end of the carrier bar 250 until a relatively heavy plate 393, Figs. 6 and 7, fixed to the rear end of the upper surface of the shield 391 underlies a longitudinal slot 394 formed in the rear portion of the carrier bar 250. A flange 396 formed on the mounting plate 318 and which overlies the rear end of the carrier bar 250, for the purpose of securing the plate 318 to the carrier bar, also has a corresponding slot 394 therein, and a headed set screw 397 extends through the slot and is threaded into the plate 393 to secure the shield in adjusted position along the slot 394. The screw 397 is rendered accessible through an elongated rearward extension 374' of the opening 374 in the lister carriage. The rearwardly facing edge 390 on the shield 391 is provided by forming an enlarged opening or slot 390' therein, and this slot 390' is of sufficient size to allow the pawls 385 to accomplish their rack advancing function after they have moved off of the edge 390 of the shield. Since the angularity of the two cams 350 and 351 may be independently adjusted, the relationship of the strokes of the line spacing slide 380 and the back spacing carrier bar 250 may be varied considerably, and after a desired adjustment has been attained in these other elements, the shield 391 is adjusted so that the pawls 385 are disabled when the paper carrier 43 is in position for the printing of the last impression from a particular printing device D.

Since the pawls 385 are thus disabled only at the end of the back spacing movement, and such back spacing occurs only in that cycle in which the last printing operation is being performed from a particular printing device, it will be evident that the present lister assures completion of the desired number of impressions from each printing device. This result is assured by the fact that until the pawls 385 are disabled it is impossible to withdraw the paper holder 43 to its

forward or normal loading position. Hence, when an operator grasps the forwardly projecting handle 400 which is provided on the paper holder, and endeavors to pull the paper holder to its forward position, the then stationary pawls 385 will tend to engage with the openings 320 of the rack so as to prevent such withdrawal unless the back spacing carrier bar 250 and the line spacing slide 380 are in their most forward positions so as to disable the pawls 385.

When the paper holder 43 is thus withdrawn in a forward direction, its movement is automatically stopped at such a point that after a new form F has been loaded thereon, the next printing impression, as 71-72, will be made in the first or top line 105 of the form. This end is attained by a stop pawl 402 which is adapted to engage with a stop opening 403 in the rack 310 when the opening 403 is brought into registry with the pawl. The pawl 402 is formed by a horizontal arm of a bell crank pivoted at 404 on the plate 318 just forwardly of the cylindrical winding housing 317. The pawl 402 projects rearwardly from its pivot 404, and by means of a spring device 405 acting on the downwardly projecting arm 402' of the pawl, the rear end of the pawl 402 is constantly biased into engagement with the lower face of the rack 310. The opening 403 is provided near the rear end of the rack and relatively close to one edge thereof, Figs. 9, 10 and 24, so that during the major portion of the forward movement of the paper holder the pawl 402 bears against a solid portion or strip of the rack, and hence the pawl 402 is ineffective until the forward withdrawing movement of the rack brings the opening 403 into registry with the pawl. The pawl 402 then enters the opening 403 and prevents further forward movement of the rack and the paper holder.

In attaining the proper location of the paper holder 43 for the performance of the first printing operation in proper aligned relationship in the first line 105 of the form F, it is necessary that the pawl 402 engage the opening 403 and stop the rack 310 in such a position that in the first line spacing movement of the line spacing slide 380, one of the pawls 385 will engage the opening 320 which pertains to the first line of the form 105. Thus the various openings 320 may be considered as being allocated one to each of the lines 105, and in Fig. 24 of the drawings the first one of the openings 320, that is, the one nearest to the opening 403, is indicated as 320-I, and correspondingly, the last one of the openings 320 is indicated as 320-L, since this particular opening is allocated to the last line 105 of the form F. The relationship of the stop opening 403 to the opening 320-I is such that when the rack has been stopped by engagement of the pawl 402 with the opening 403, the next operation of the line spacing slide 380 will cause one of the pawls 385 to engage the opening 320-I, and hence in the first machine cycle the form F will be advanced so that the first impression will be made in the proper relationship in the top line 105 of column 90 of the form F. The distance between the opening 403 and the last spacing opening 320-I is related to and determined by the upper marginal dimension 111 of the form F, and hence the pawl 402 may be referred to as a means for automatically determining the top margin of the form F.

The flexible rack 310 is also utilized to automatically attain the proper bottom margin, and

this end is attained through the provision means which is controlled by an advancing movement of the flexible rack 310 and is operable to govern the auto-stop means of the printing machine. To this end a detecting means such as a pawl 410 is mounted just forwardly of the pawl 402, the pawl 410, Figs. 6 to 11, inclusive, being in the form of a bell crank, one of the arms of which provides the pawl 410. The pawl 410 is pivoted on a stud 411 carried in the mounting plate 318 just forwardly of the mounting stud 404, and an arm 412 of this bell crank extends downwardly substantially parallel to the arm 402' of the pawl 402. The spring device 405 is arranged in the present instance to act between the arms 402' and 412 so as to act as a spring biasing means for both of the pawls, there being suitable mounting blocks 413 carried pivotally on the two arms 402' and 412 so that a guide pin 414 may extend between and slidably through the two mounting blocks 413. Intermediate the two mounting blocks 413 an expansive coil spring surrounds the pin 414 so that the spring acts to urge the pawls 402 and 410 upwardly into contact with the bottom of the flexible rack. When the pawl 410 is engaged with the bottom of the rack 310, a roller 415 carried on the lower end of the arm 412 engages one contact arm 416' of a normally closed spring contact switch 416 to maintain the switch 416 open. The switch 416 constitutes a detecting switch or control switch similar to switch 187, Fig. 26, which when closed serves to energize the auto-stop solenoid 181 to thereby stop the continuous operation of the printing machine 40. In the present instance the two contacts of the switch 416 are connected by wires 418 and 419 to a plug connector 420 which may be inserted into a plug outlet 421 provided in the left-hand end of the frame 42 of the printing machine. The two conductors 418 and 419 are provided by a conventional two-wire cord which is indicated at 418' in Fig. 1 of the drawings. The two terminals of the outlet socket 421 are connected by wires 422 and 423 across the switch 187, or in other words the wire 422 is connected to the wire 188 and the wire 423 is connected to the wire 186. Thus, when the switch 416 is closed, the auto-stop solenoid 181 is energized in the same manner as hereinbefore described with reference to the switch 187.

The pawl 410 has a pointed end which is adapted to be projected through an opening 431 formed in the flexible rack 310 adjacent to the opening 320-L which is allocated to the last line 105 of the form F. The opening 431 is located near the same side edge of the rack 310 as the opening 403, and hence the opening 431 is not engaged by the pawls 385 at any time. When the opening 320-L is engaged in the course of a line spacing operation so as to advance the paper holder and bring the last line 105 of the form F into position for the printing of the desired impression in the first column 90 thereof, the opening 431 is brought into alignment with the pointed end of the pawl 410. It will be recognized, however, that automatic or continuous operation of the machine should not stop at this time, since the printing machine must operate through another printing cycle in order to print the related data in the second column or column 91 of the last line 105 of the form. Means is accordingly provided for delaying the operation of the auto-stop means and this end is accomplished through the provision of a stationary timing cam 440. The timing cam 440 is mounted by means

5 of screws 441 on the top of the bracket 217, Figs. 6, 7 and 11, and the cam 440 projects in a rearward direction substantially parallel to the pawl 410 as will be apparent in Fig. 7. A pin 442 projects from the pawl 410 so as to underlie the timing cam 440.

10 Since the pawl 410 is mounted on the carrier bar 250, so as to travel back and forth therewith, the pin 442 rides along the lower edge surface 15 of the stationary cam 440, and while the carrier bar 250 is in its rearward position of Fig. 11 the pin 442 engages a dwell surface 444 of the cam 440 which holds the pawl 410 against upward movement even though the opening 431 may be aligned with the pawl 410. Thus, when the 20 operation of the line spacing slide 380 initially aligns the opening 431 with the pawl 410, the pawl is, nevertheless, retained in its lower position until the last, or second printing operation in the last line of the form, has been initiated. 25 During the first part of the second printing cycle however, the back spacing slide 250 shifts the pin 442 along the dwell surface 444, to the left in Fig. 11, and the pin 442 is thereby moved into alignment with a cam recess or notch 445 formed 30 in the cam 440. Thus the pawl 410 is freed for upward movement, and since the flexible rack 310 has moved with the carrier bar 250 and the pin 442 during the back spacing movement, the opening 431 is still aligned with the pawl 410 and the nose of the pawl passes into the opening 431. As 35 a result the switch 416 is allowed to close and the auto-stop solenoid 181 is energized so as to stop operation of the machine when the printing impression in the last line of the last column has been completed.

It may be observed that the pawl 410 is similarly freed for upward movement whenever the machine is performing its last printing operation 40 in each line 105 of the form, but until the opening 431 has been properly aligned, the pawl engages a solid area of the rack 310 and is thereby maintained in a switch opening position.

45 After the auto-stop solenoid 181 has been energized so as to stop the operation of the printing machine, the operator removes the completed form F from the paper holder 43. This is accomplished through forward withdrawal of the paper holder and it will be evident that, as an 50 incident to such withdrawal, the forward movement of the opening 431 acts upon the end of the pawl 442 to cam the same in a counterclockwise direction. This results in the opening of the switch 416 so that the machine is again conditioned for operation under the control of the 55 auto-stop plunger 180.

When an operator wishes to dismount the paper holder 43, the upper margin control pawl 402 may be manually released by actuation of a projecting pin 402'' carried by the associated block 413, as shown in Fig. 7.

The cam mechanism 200 whereby the transverse shifting movement is imparted to the lister carriage 44 is best shown in Figs. 16 to 19, inclusive, of the drawings wherein it will be evident that the cam mechanism 200 is located just to the right of the right-hand end of the main drive shaft 151. The cam mechanism 200 comprises a drum type cam 450 carried in a mounting bracket 451 which is secured on the forward side of the mounting rail 153 of the printing machine. The mounting bracket 451 provides a pair of forwardly and downwardly extending arms 452 and the cam 450 is rotatably mounted between the arms 452 on a bearing shaft 453. Beneath

the cam 450 a rotatable shaft 455 is journaled in suitable bearings provided in the arms 452 so that the shaft 455 is aligned with the main drive shaft 151. Means is provided intermediate the adjacent ends of the shafts 151 and 455 whereby the shaft 455 may be connected to the drive shaft 151, this means in the present instance comprising a one-revolution clutch 456, and the rotative movement imparted to the shaft 455 is transmitted to the cam 450 by means of a pair of meshed gears 457 and 458. The gear 457 is pinned on the shaft 455 while the gear 458 is mounted on the shaft 453 and is connected to the cam 450 by means of a longitudinal pin 459. The ratio of the gears 457 and 458 is dependent upon the number of columns in which the printing matter is to be distributed on the form F, and since the embodiment of the invention shown in Figs. 1 to 20 of the drawings provides for the performance of two column listing operations, the ratio between the gears 457 and 458 is herein shown as being 2 to 1, thereby providing for a 180° movement of the cam 450 each time the shaft 455 is operated through a complete revolution.

The mounting bracket 451 is connected to the mounting rail 153 by a pair of horizontal bolts 460 and by a vertical bolt 461, and on the lower end of the bolt 461 a mounting sleeve structure 462 is secured, this sleeve structure being arranged to engage a pivot opening 463 provided in the actuating lever 201. The forward end of the actuating lever is arranged to be disposed directly beneath the mounting shaft 453, and a cam roller 465 is mounted on the upper face of the forward end of the lever 201 for engagement with a cam groove 466 formed in the cylindrical surface of the cam 450. The cam 450 is shown in Fig. 16 in the rest position which it occupies when the lister carriage 44 is in its right-hand position of Fig. 2. When rotation is imparted to the shaft 455, this rotation is transmitted to the cam 450 so as to rotate the same in the direction indicated by the arrow in Figs. 16 and 17, and in such movement a leading surface 467 engages the cam roller 465 to shift the forward end of the lever 201 to the right, with the result that the rear end of the lever 201 imparts a left-hand movement to the lister carriage 44. The cam 450 is so formed that this left-hand movement is completed during slightly less than a 90° advancing movement of the cam 450, at which time a dwell portion 468 of the cam engages the roller 465 and maintains the lister carriage in the desired left-hand position. The rotative movement of the cam 450 is terminated after 180° of movement. In the next cycle of operation of the machine a leading surface 469 of the cam groove 466 engages the roller 465 so as to shift the same from a right-hand position to a left-hand position, and such movement of the cam roller causes the carriage 44 to be shifted back toward its right-hand position. The leading surface 469 accomplishes the desired shifting movement of the lister carriage in slightly less than a 90° movement of the cam 450, and the cam then continues through the additional 90° movement while the cam roller 465 is engaged with a dwell surface 475. The actuating movements of the lever 201 are in the present instance rendered exceptionally smooth through the provision of a pair of oppositely acting tension springs 475 which are connected to an up-standing pin 476 provided on the rear portion of the lever 201, and the opposite ends of the

springs 475 are connected to anchoring pins 477 which project rearwardly from the mounting rail 155 on opposite sides of the mounting bolt 461. Thus the lever 201 is urged toward a central position and the spring 475 which has been tensioned in a previous machine operation acts to augment the driving force of the cam in starting the next shifting movement of the lister carriage 44.

The movement of the lever 201 is transmitted to the lister carriage 44 in such a manner that while the stroke of the cam 450 is constant, an appreciable adjustment or variation may be attained in the length of the transverse stroke of the lister carriage 44, and hence this adjustment provides for variation of the column spacing in the form F. In the present instance the rear portion of the lever 201 has a longitudinal slot 480 formed therein, and the link 202 may be connected to the lever 201 at any point along the slot 480 through the medium of a screw and nut device 481. In Fig. 19A of the drawings the screw and nut device 481 is shown in detail and it will be evident that the screw and nut device comprises a bearing stud 481' about which an opening 482 in the end of the link 202 is positioned. The link is held in position on the bearing portion of the stud 481' by a screw 483 which has an enlarged head for manual tightening of the screw. The screw 483 is threaded into the bearing stud axially thereof and the head is of such a size as to overlie the upper surface of the link 202 and hold the same in place.

Beneath the bearing portion the stud has a peripheral flange 484 which rests upon the top of the lever arm 201, and a downward extension of the stud provides a non-circular portion 485 which is slidably but non-rotatably positioned within the slot 480 of the lever 201. Beneath the lever 201 the stud has a downwardly extending screw-threaded end, and a washer 486 and a clamping nut 487 are positioned on the screw-threaded lower end so the bearing stud may be clamped in any desired adjusted position along the slot 480. Such a position of adjustment may, if desired, be permanently marked upon the lever 201 by means of an index groove or line formed in the upper surface or in an edge surface of the lever 201. A corresponding index mark is preferably placed upon the peripheral flange 484 of the stud 481' for cooperation with index marks which have been placed upon the lever 201. It will be evident that when a desired position of adjustment for the bearing stud structure has been established to thereby attain the desired length in the transverse stroke of the lister carriage 44, this adjusted position may be maintained when the lister is removed from the printing position since such removal requires only the unloosening and removal of the retaining screw 483. The bearing stud structure remains in adjusted position on the lever 201 and when the lister is returned to its position on the printing machine, it is only necessary to reconnect the link 202 to the previously adjusted bearing stud structure 481'.

The clutch 456 comprises a driving member in the form of a collar 490 and a driven member in the form of a hollow housing 491 within which the driving member 490 is located. The driving member 490 is fixed on the shaft 151, and the driven member 491 is pinned to the shaft 455. The driven member 491 has a clutch pawl 492 mounted therein on a pivot 493 located inter-

mediate the ends of the pawl, and on one of its ends the clutch pawl 492 has a tooth 494 which is urged by means of a spring 495 towards an engaged relationship with respect to a notch 496 formed in the driving member 490. The other end of the clutch pawl 492 has a tooth 497 which projects readily outwardly through an opening 498 provided in the periphery in the driven member 491. The spring 495 tends normally to engage the tooth 494 with the notch 496, thereby normally to tend to drive the driven member 491 with the driving member 490. Means is provided, however, to disengage the clutch pawl and this means in the present instance comprises a plurality of stop levers 500, 501 and 502 which are generally similar in form and are pivoted intermediate their ends on a mounting shaft 505 carried in the bracket 451. Each of the stop levers has a hook-like end 506 which may be disposed in an active position such that when the driven member is being actuated in a clockwise direction, Fig. 18, the projecting tooth 497 of the clutch pawl will engage the hook-like end 506 at a particular point in the rotative movement of the driven member, with the result that the clutch pawl 492 will be pivoted to its released relationship of Fig. 18 and the driven member 491 will be stopped in a predetermined rotative relationship. In the present instance the proper or desired positioning of the driven parts is maintained while the clutch is disengaged through the action of a latching means acting on the driven member 491. As herein shown, this latching means comprises a latching lever 508 having an arcuate recess 509 therein adapted to engage with a roller 510. The roller 510, as shown in Fig. 17 of the drawings, projects to the right from the driven member 491 so as to be located beneath the latching lever 508, and a spring 511 urges the latching lever 508 toward its active position.

The three stop levers 500, 501 and 502 are arranged to accomplish the same ultimate function which is to prevent engagement of the clutch 456, and each of the three stop levers is governed by a different means. Thus the stop lever 500 is operatively associated with the control mechanism of the platen P, the stop lever 501 constitutes an off-on control lever governed by a lister control plunger 515 mounted in the front panel of the printing machine, while the stop lever 502 constitutes a means whereby the operation of the lister mechanism is dominated by the selector mechanism of the printing machine. The connection between the control plunger 515 and the off-on stop lever 501 is provided by a link 516 which extends rearwardly from the plunger 515. The rear end of the link 516 is connected to a swivel block 517 mounted on the upper end of a rocker arm 518. The rocker arm 518 is fixed to one end of a sleeve 519 mounted in a surrounding relationship upon a horizontal rock shaft 520. The sleeve 519 is capable of independent rocking movement about the axis of the shaft 520, and at its other end the sleeve has an arm 521 fixed thereto. The arm 521 extends in a forward direction from the sleeve 519 and the lower end of a substantially vertical link 522 is connected to the end of the arm 521. At its upper end the link 522 is connected to the rearwardly projecting end of the stop lever 501. Thus, when the plunger 515 is in its rearward position, the arm 521 is located in the position shown in Fig. 19 of the drawings.

When the arm 521 is thus positioned the arm 521 at the other end of the sleeve is so located as to shift the rear end of the stop lever 501 upwardly. This causes the hook-like end of the stop lever 501 to be located in its active position so as to prevent operation of the lister driving cam 450. When an operator wishes to utilize the lister 41, the control plunger 515 is withdrawn in a forward direction, thereby to rock 10 the sleeve 519 in a clockwise direction as viewed in Fig. 19 and cause the stop lever 501 to be withdrawn to an inactive position wherein it is maintained throughout the period of use of the lister 41. When the control plunger 515 is thus withdrawn, the lever arm 521 assumes the position shown in dotted outline at 521 in Fig. 18 of the drawings.

Assuming for the moment that the stop levers 501 and 502 have been shifted to their withdrawn 20 or inactive positions, the stop lever 500 may be actuated from its active relationship of Fig. 18 to institute a cycle of operation of the lister cam 450. It is desirable, of course, that the lister cam 450 be rendered active in timed relation to 25 the operation of the platen mechanism P, and this end is attained through interconnection of the stop lever 500 of the lister clutch with the stop lever 156' of the platen clutch 156. Thus, as shown in Figs. 16, 17, 18 and 20, a connecting 30 block 530 is mounted by means of a set screw 531 on the vertically extending link 158 which is utilized to release the stop lever 156'. An upward extension 532 on the right-hand side of the block 530, Figs. 16 and 17, has a transversely or 35 horizontally extending pin 533 mounted thereon, and this pin extends through an opening 534 formed in the rearwardly projecting arm portion 500' of the stop lever 500. Thus, when the link 158 is withdrawn momentarily in a downward 40 direction for the purpose of releasing the stop lever 156' of the platen clutch, the stop lever 500 of the lister clutch is similarly actuated and is shifted to its inactive position at the same 45 time. Thus, the cycle of operation of the lister mechanism is instituted concurrently with the operation of the platen mechanism P.

As hereinbefore pointed out, the printing machine 40 embodies a selector mechanism, and such selector mechanism is operable in response 50 to the sensed presence or absence of identifying means such as tabs 65 at selected identifying positions on a printing device to cause the printing machine to skip certain of the printing devices which are passed through the printing machine. 55 In such operation of the selector mechanism the primary stop lever 156' of the platen clutch 156 is actuated in the same manner as if a printing operation were to be performed, but the platen mechanism is prevented from operating through 60 the dominating action of a supplemental stop lever 156'' which is normally in an inactive position and is shifted to an active position whenever a particular printing device is to be skipped. The construction and operation of the selector 65 mechanism and the manner in which this selector mechanism actuates the supplemental stop lever 156'' of the platen clutch are fully described in my copending application Serial No. 392,151, and reference may be had to this copending application for further details of such construction and operation. For present purposes it will be sufficient to point out that the selector mechanism includes the shaft 520 as a part thereof, and whenever a particular printing device is to 70 be skipped, the shaft 520 is yieldingly actuated 75

in a counterclockwise direction, as viewed in Figs. 18 and 19, so as to shift the supplemental stop lever 156'' of the platen clutch into its active position. Such shifting movement takes place in the cycle of machine operation which immediately precedes the cycle in which the particular printing device is to be located at printing position, so that the actuation of the supplemental stop lever 156'' to its active position is in the nature of a conditioning operation in that it is conditioned to prevent operation of the platen mechanism in the next cycle of machine operation. The selector shaft 520 is operatively associated with the supplemental stop lever 156'' by means of an arm 540 fixed on and projecting generally forwardly from the shaft 520 and having a link 541 connected between the end of the arm 540 and a rearwardly projecting arm portion of the supplemental stop lever 156''. Thus, when the selector shaft 520 is rocked in a counterclockwise direction as viewed in Figs. 18 and 19, the end of the arm 540 is elevated and since this elevates the rear end of the stop lever 156'', the hook-like end of the supplemental stop lever 156'' is shifted to its active position.

When the selector mechanism acts through its rock shaft 520 to thus condition the platen clutch so as to skip the next printing device, the lister clutch 456 is similarly conditioned through a similar shifting movement to the stop lever 502 thereof to its active position. To this end an arm 550 is fixed on the selector shaft 520 so as to project forwardly therefrom in the same general manner as the arm 540, and a link 551 extends upwardly from the end of the arm 550 and is connected to the rearwardly projecting end of the arm 550, as shown in Figs. 17 and 18. Thus, when the selector shaft 520 is rocked in a counterclockwise direction as viewed in Fig. 18, the arm 550 is moved from its horizontally projecting position of Fig. 17 to the position shown in Fig. 18, and as a result the stop lever 502 of the lister clutch is shifted to its active position, as shown in Fig. 18. Hence, when the operating link 158 connected to the stop lever 156' of the platen clutch is shifted downwardly to release the primary stop lever 156 of the platen clutch and the primary stop lever 500 of the lister clutch, the two supplemental stop levers 156'' and 502 remain in their active positions so as to prevent operation of the platen mechanism P and the lister 41.

The foregoing description of the manner of operation of the supplemental stop lever 156'' of the platen clutch and the supplemental stop lever 502 of the lister clutch has been based upon the manner in which these parts function in the event that the machine is being controlled by the consecutive foot pedal 142, but it will be realized that when the machine is operating under the control of the auto-stop means the normal stop lever 156' of the platen clutch and the stop lever 500 of the lister clutch will be maintained constantly in their withdrawn positions. Hence the two clutches will be controlled solely by the supplemental stop levers 156'' and 502. The platen clutch 156 and the lister clutch 456 will therefore remain engaged at all times except when a particular printing device is to be skipped and at this time the two stop levers 156'' and 502 will be rendered active in the manner hereinbefore described to maintain the platen clutch and the lister clutch disengaged.

In the embodiment of the invention disclosed in Figs. 1 to 20 the arrangement of the cams 350

and 351 is such that the last printing operation to be performed in each line 105 of the form produces a printing impression in the second or right-hand column 91 of the form F. This result follows from the fact that the line spacing operation is performed during the left-hand stroke or movement of the lister carriage 44. In Fig. 25 of the drawings an embodiment of the two column lister of the present invention is illustrated whereby the columnar printing sequence of the lister is reversed. Thus, in the embodiment shown in Fig. 25 the mounting plate 352 for the cams 350 and 351 is secured upon the mounting rail 211 near the left-hand end thereof, while the adjusting plate 354 is secured to the mounting rail 211 near the right-hand end thereof. Thus the angular relationship of the cams 350 and 351 with respect to the path of reciprocation of the lister carriage 44 is in effect reversed in this embodiment of the invention. Hence the line spacing movement is imparted to the paper holder during the right-hand stroke of the lister carriage 44, and when the line spacing movement has been completed, the second column of the form is aligned with printing position. Thus the first printing impression which is made from one or more of the upper lines of the printing device is made in the second column or column 91 of the form. When the movement of the lister carriage 44 is reversed and it is shifted back to its left-hand position, the back spacing movement is imparted to the paper holder 43, thereby to cause the second impression from a particular printing device to be made in the first column or column 90. Such reversal of the sequence in which the printing impressions are made in the two columns of the form is accomplished in the lister of the present invention merely by reversing the mounting of the plates 352 and 354 and the two cams 350 and 351, and it will be observed that the cams are so located and so mounted that such reversal may be readily accomplished. As a result a lister to meet the demands of the various types of work may be provided with but a minimum amount of readjusting work and this work may be accomplished without the provision of additional or different parts or elements.

In the preparation of certain classes of business forms involving two column listing operations, it is desirable to skip one or more lines 105 of the form, and in Figs. 27 and 28 of the drawings I have illustrated an embodiment of the present lister whereby the operator is enabled to accomplish such spacing manually at any point in the listing operations performed by the machine. In this embodiment of the invention the line spacing cam has an operative cam surface 381' which is similar in form and function to the cam surface 381 embodied in the cam 350 of Fig. 62, but in this embodiment the opposite edge 560 of the cam slot is spaced a substantial distance from the cam surface 381' so that the cam roller 382 may be shifted rearwardly away from the cam surface 381' in certain instances to thereby actuate the line spacing slide 380 through an operative movement while the lister carriage 44 remains stationary. Such movement may be imparted to the line spacing slide through a medium of a link 562 which has its rear end connected to the stud 383 of the line spacing slide. The link 562 extends in a forward direction along the center line of the lister carriage 44 and through the medium of a longitudinal slot 564 which embraces the stud 376 of the roller 372, the link 562 is guided for longitudinal reciprocating move-

ment. The link 562 is normally urged in a rearward direction by means of a spring 565 which acts between a stud 566' on the link and a stationary anchoring stud 566 mounted on the lister carriage 44. If desired, such a spring bias may be attained by a spring 372' mounted between the studs 378 and 382 in the manner shown in Fig. 2. The forward end of the link 562 is pivoted at 567 to one end of an actuating lever 568. The actuating lever is pivotally mounted intermediate its ends on an upstanding stud 569 mounted on the lister carriage 44, and the other end of the lever 568 has a finger piece 570 formed thereon whereby the lever 568 may be actuated. When an operator wishes to impart a manual line spacing movement to the paper holder 43, the finger 570 is engaged and withdrawn in a forward direction, thereby to impart a rearward movement to the link 562 and to the line spacing slide 380.

It will be recognized, of course, that the printing machine must be stopped in order to perform a manual line spacing operation as aforesaid, and in most instances it is desirable to perform such a manual line spacing operation after the last printing impression has been made in a particular line 105 of the form. For this reason the line spacing cam in the present instance is formed so that when the lister is located in the position which it occupies when the first printing impression is made from a printing device, the manual line spacing means is in effect disabled. This end is attained by arranging the surfaces 381' and 560 in a tapered relationship. As shown in Fig. 27 ample space is provided between the edge surfaces 381' and 560 near the right-hand end of the line spacing cam so that the manual line spacing means would be inoperative to produce a line spacing movement of the paper holder 43.

In some classes of printing work it is desirable to distribute the data carried by a printing device in a larger number of columns, as for example in three different columns, and in Fig. 29 of the drawings I have illustrated a three column lister embodying the features of the present invention. In the three column lister the same general type of lister frame 45 is employed, the only difference being that the side frames 288 are spaced apart a greater distance than in the two column lister shown in the preceding figures of the drawings. The mounting plate 352 and the adjusting plate 354 are also generally similar to the corresponding parts employed in the two column lister. In the three column lister, however, a different line spacing cam 758 and a different back spacing cam 751 are provided, these cam members being, however, mounted in the same general manner upon the mounting plate 352 and the adjusting plate 354. The printing device D-2 which has been selected for purposes of illustration is best shown in Fig. 32, and this printing device is one embodying eight lines of type characters which are grouped in three different groups for distribution with one of these groups in each of the three columns of the form F-2. In the particular printing device which has been illustrated in Fig. 32 three separately formed printing plates 761, 762 and 763 are utilized in providing the several lines of type characters, and in the present instance each of the printing plates is arranged to carry one of the groups of type characters. Thus the upper printing plate 761 has three lines of type characters 771, 772 and 773 formed thereon with an equal line spacing dimension between the sev-

eral lines as indicated at 780. These three lines of type characters constitute the first group which is to be printed in column 91 of the form F-2. The intermediate printing plate 762 carries three lines of type characters 774, 775 and 776 which are equally spaced as indicated at 781. It will be observed, however, that a somewhat larger line spacing dimension 782 is required between the lower line 773 of the upper plate and the top plate of the intermediate plate. The lower printing plate 763 carries two lines of type characters 777 and 778 which are arranged with a line spacing dimension 783 which is the same as the spacing 780. A somewhat larger line spacing dimension 784 is required between the two lines 776 and 777 due to the fact that these lines are formed on different printing plates. The lines 774, 775 and 776 constitute the second group which is to be printed in the second column of the form F-2, while the lines 777 and 778 constitute the third group which is to be printed in the third column or column 92 of the form F-2. Where three such groups are to be printed in successive printing operations, it will be recognized that the automatic plate mechanism will be correspondingly modified so as to bring appropriate platen faces PF into successive cooperation with the three groups of type characters. Moreover, it will be evident that the printing device D-2 must be maintained at printing position for three printing cycles, and the multi-print mechanism of the printing machine is accordingly set up to attain the desired control with respect to the printing device feeding mechanism.

In distributing the three groups of type characters in the three columns of the form F-2 it is, of course, desirable to attain a predetermined alignment of the various lines of printed type characters in the several columns of the form, and this end is attained through appropriate advancing and back spacing movements imparted to the paper holder 43 as an incident to the transverse shifting of the lister carriage.

The transverse shifting movement of the lister carriage 44 is accomplished in such a manner that the lister carriage comes to rest at three different positions along its path of transverse movement, and in each of these three positions a different one of the columns of the form F-2 is aligned with the printing position. Such movements, of course, are based upon the column spacings of the columns, as indicated at 115' and 116' in Fig. 30. In attaining this mode of operation the lister cam 450' is driven from the lister clutch 456 in a 1 to 3 ratio, the gearing 451, 458 being appropriately modified to accomplish this result. Thus the lister cam 450' rotates through 120° in each operative cycle of the printing machine. In the present embodiment of the three column lister the lister carriage is initially located in the right-hand position shown in Fig. 29 of the drawings, this position being the one in which the last printing operation pertaining to a particular printing device D-2 is performed. Thus when the lister carriage is located in this initial position, the third column or the column 92 of the form F-2 is aligned with the printing position of the printing machine. In the first printing cycle of the printing machine the lister carriage 44 is actuated to the left in Fig. 29 to such a point that the second column 91 of the form is aligned with printing position, and while the lister carriage is so located the desired printing operation is performed in the second column 91 of the form. In the

second operation or cycle of the printing machine pertaining to a particular printing device D-2 the lister carriage is shifted further to the left until the first column or column 90 of the form F-2 is aligned with printing position, and while the lister carriage is maintained stationary in this relationship the desired printing impression is made in the first column or column 90. Since the third cycle of operation requires that the lister carriage be returned to its first or right-hand position, the present invention accomplishes a part of this movement during the last portion of the second cycle. Thus after the second printing operation has been completed and the upward withdrawal of the platen roller has started, the return or right-hand movement is started, and as a result the carriage 44, at the end of the second cycle, is located intermediate its left-hand and medial positions. In the third cycle of the printing machine pertaining to the particular printing device the lister carriage 44 is returned to the right until it reaches the position shown in Fig. 29, bringing the third column or column 92 of the form F-2 into alignment with the printing position, and while the lister carriage is maintained stationary in this position the desired printing impression is made in the third column of the form.

The cams 750 and 751 of the lister illustrated in Fig. 29 are constructed and arranged so that in the shifting movement of the lister carriage from its right-hand position to its central position of Fig. 29 the desired line 105 of the form F-2 is brought into alignment with the intermediate lines of type characters of the printing device, or in other words into alignment with the lines 114, 115 and 116 of the printing device D-2. Such shifting movement of the form F-2 involves two increments of movement, the first of which is equal to the line spacing 110 of the form F-2, Fig. 31, and the second of which is equal to the spacing between the lines 114 and 117 on the printing device D-2, this latter increment of movement being indicated at 791 in Fig. 32 of the drawings. After the performance of the printing operation in the central column 91 of the form F-2 the paper holder has an additional line spacing or aligning movement imparted thereto by the line spacing cam 750 and this additional movement is such that the printing impressions 114', 115' and 116' are brought into alignment horizontally with lines 111, 112 and 113 of the type characters on the printing device D-2 at printing position. Hence the advancing movement imparted to the paper holder in the course of transverse movement of the lister carriage from its middle location to its left-hand location is equal to the line spacing between the lines 111 and 114 on the printing device D-2, this distance being indicated at 792 in Fig. 32 of the drawings. When the lister carriage is returned from its left-hand position to its right-hand position for the performance of the printing operation in the third column 92 of the form, the paper carriage is back spaced in an amount sufficient to align the printing impressions 111' and 114' with the line 117 of type characters on the printing device D-2 at printing station, and this movement is equal to the line spacing between the lines 111 and 117 as indicated at 793 in Fig. 32.

In accomplishing the line spacing and back spacing movement as hereinbefore outlined, the cam slots in the cams 750 and 751 are arranged to provide dwell portions at substan-

tially the midpoints of the two cams. Thus the line spacing cam 750 has a cam slot 800 having a dwell portion 801 substantially midway between its ends in such a location that when the central column 91 of the form F-2 is aligned with the printing position, the cam roller 382 of the line spacing slide 380 is located in the dwell 801. To the right of the dwell portion 801 the cam slot 800 has a lead portion 802 along which the cam roller 382 travels during movement of the lister carriage from its central position to right-hand position. To the left of the dwell portion 801 the cam slot 800 has another leading portion 803 which imparts movement to the cam roller 382 as the lister carriage 44 moves from its central position to its left-hand position. A similar central dwell portion 810 is provided in the cam slot 810 of the back spacing cam 751, and a similar right-hand leading portion 812 and a similar left-hand leading portion 813 are provided in the cam slot 810, and the slopes or leading angles of the various leading surfaces of the two cam slots are correlated with the column spacings of the form F-2 in such a manner as to attain the desired advancing and back spacing movements as set forth hereinabove.

It will be recognized that it is desirable to provide for operation of the three column lister with forms embodying different column widths or column spacings, but in this connection it will be observed that when the central column of a form is located in registry with the printing position, the lister carriage 44 must be so located that the cam rollers 372 and 382 will be engaged with the medial dwell portions of the cam slots. In accomplishing this purpose provision is made in the driving mechanism for the lister carriage whereby, after the link of the stroke of the lister carriage has been adjusted, the location of this stroke may be adjusted so that the central rest position of the carriage 44 is located so as to correspond with the location of the dwell portions of the cams. To this end the cam 450' is arranged to drive a relatively short actuating lever 201' which terminates just forwardly of the rear wall 208 of the printing machine, and the rear end of the lever 201' is connected by means of a link 820 to an arm 821. The arm 821 is pivoted on the lower end of a mounting bolt 822 which projects downwardly through the rear rail 153 of the printing machine frame. The arm 821 projects rearwardly through a slot 823 formed in the rear wall 208 and is connected to the lister carriage 44 by means of a longitudinally adjustable link 825. The link 825 is connected by means of a screw and nut device 826 at any desired point of adjustment along a longitudinal slot 821 formed in the arm 821, the length of the stroke of the lister carriage 44 being adjusted by varying the point of connection of the link 825 with the arm 821. The adjustable link 825 is formed in two sections which are adjustably connected together by means of screw and nut devices 828 which pass through one of the sections of the link 825 and engage a slot 829 formed in the other one of the sections, so that after adjustment of the stroke length the location of the stroke may be varied to suit the form of the cams.

The lever 201' is biased toward a central position by springs 475', thereby to assure smooth cooperation of the cam roller 465' of the lever with the cam slot of the drive cam 450'. In Fig. 29 of the drawings the cam 450' is shown in the at rest position which it occupies after the per-

formance of the last printing operation from a particular printing device D-2. In each machine cycle the cam 450' moves through 120°, to attain the various lateral shifting movements as hereinabove outlined, the advancing movements of the cam 450' are utilized in the following manner. In the first machine cycle pertaining to the next printing device D-2 the cam roller 465' is engaged by a leading surface 840 of the cam 450' and in substantially 54° of rotative movement of the cam 450' the cam roller 465' is engaged by a dwell surface or groove 841 of the cam, and the dwell surface 841 is so formed that the lister carriage 44 is thereby positioned at midpoint of its stroke. This aligns the second column or column 91 of the form F-2 with printing position so that the desired printing impression may be made in this column while the last 66° of movement of the cam 450' moves the dwell surface 841 along the cam roller 465'. At the 20 end of this cycle the cam roller is engaged with the trailing end portion of the dwell 840, and in the next cycle of the printing machine the cam roller 465' is immediately engaged by a leading surface 842 of the cam groove. In substantially 54° of advancing movement of the cam 450' the lister carriage 44 is shifted to its left-hand position, and a dwell surface 843 of the cam is brought into engagement with the cam roller 465'. The dwell surface 843 extends through substantially 46° so that the lister carriage is maintained stationary with the first column or column 90 of the form F-2 in alignment with printing position so that the desired printing impression may be made in this column. Such a dwell period affords time for completion of the printing operation in the column 90, and during the balance of the cycle, or substantially 20° of rotative movement of the cam 450' the cam roller 465' is engaged by a reversely extending leading surface 844. Thus a part of the return or right-hand movement of the carriage is accomplished during the last portion of the second cycle. In the third cycle the leading surface 844 continues the return movement of the carriage, and this movement is completed within substantially 54° of movement of the cam 450' in the third cycle. The cam roller 465' is then engaged by a dwell surface 845 so as to maintain the lister carriage 44 stationary in its right-hand position with the third column or column 92 of the form F-2 aligned with printing position, thereby to enable the desired printing operation to be performed in this column. At the conclusion of this particular cycle of operation the cam roller 465' occupies the position shown in Fig. 29 of the drawings and is thereby conditioned to repeat the foregoing sequence of operations with relation to the next printing device D-2. It will be recognized, of course, that the three groups of type characters which are distributed in the different columns of the form F-2 may be arranged differently on the printing device D-2, or in certain instances different lines might be selected from the printing device for printing in the different columns of the form. It will also be evident that different line spacing arrangements on the plate D-2 might be employed and the present lister may be adjusted or set up to attain the desired alignment of the printing impressions in each line of the form F-2 despite the use of different line spacings on the printing devices. In the three column lister, however, there are many instances where new cams 750 and 751 will be required to

meet varying conditions, so that this embodiment does not attain adjustability in the same degree as the two column embodiment.

With the three column lister of Fig. 29 it will be evident that the automatic control of the top and bottom margins may be attained in the same manner as hereinbefore described with relation to the two column embodiment of the invention, and in addition the three column lister is capable of reversal in the same manner as the two column lister to correspondingly change the sequence of the printing operations in the several columns of the form. In the event that such reversal is desired, however, the cam 450' is replaced so as to provide for a true reversal of the shifting movements of the lister carriage. The arrangement for manual spacing of the paper holder may also be employed with the three column lister.

Operation

When an operator wishes to use the two column lister of the present invention with a printing machine such as the printing machine 40, the lister is mounted on the upper rear edge of the printing machine through engagement of the headed studs 225 with the keyhole slots 228 formed in the rear wall 208 of the printing machine. After the lister frame 45 has been shifted laterally to engage the headed studs with the small ends of the keyhole slots the rabbeted groove 231 formed on the mounting foot of the lister frame rests on the top of the mounting bar 230 of the printing machine so that the attachment screws 234 are aligned with the threaded openings 233 in the mounting bar. The attachment screw 234 may therefore be threaded into the openings 233 to secure the lister in position on the printing machine. Through appropriate manipulation of the headed mounting studs 235 and the adjusting screws 237 the lister may be disposed so that the paper holder 43 will move in a plane substantially parallel to the plane of the table top T.

The connector plug 420 is then inserted into the outlet socket 421, thereby to connect the control switch 416 of the lister with the auto-stop mechanism of the printing machine.

The dimensioning of the form F which is to be used is, of course, controlling as to the particular adjustments or set-up arrangements to be employed in the lister, and to facilitate such adjustments, a flexible rack 310, dimensioned in accordance with the line spacing, the top margin 50 dimension and the bottom margin dimension of the selected form, is first mounted in position in the lister. This is readily accomplished through securing the slot 311 of the flexible rack in position about the projecting stud 312 carried on the paper holder 43. The paper holder 43 is then mounted in position on the back spacing carrier 250 through engagement of the flange plates 262 of the paper holder with the outwardly facing grooves 261 of the carrier 250. In 60 this operation the flexible rack 310 is threaded into the inwardly facing grooves 315 of the carrier 250 and the paper holder 43 is shifted rearwardly until the rear end of the flexible rack passes beneath the two line spacing pawls 385 and through the openings 316 and 319 into the coiling receptacle 317.

The multiprint mechanism of the printing machine is then set up to maintain each printing device at printing position for two operative cycles of the printing machine, this set-up of

the multiprint mechanism being obtained in the printing machine herein shown through mounting of a suitable cam and ratchet in the printing machine. The multiprint mechanism is, of course, rendered operative through withdrawal of the control plunger 161 thereof.

The automatic platen mechanism is also adjusted and rendered operative, and such adjustment of the automatic platen mechanism includes the mounting of a suitably formed platen roller PR having platen faces PF thereon, formed in accordance with the selection of lines or type characters which are to be printed in the different columns of the form F. The automatic platen mechanism is also set up so as to appropriately shift the different platen faces into the desired operative relationship with the printing device in successive operations of the printing machine. In this connection it will be evident that in some instances where the lines of type included in the different groups to be printed in the different columns are of the same size, the same platen face PF might be employed with respect to the two groups, the desired selection being attained in such an instance through appropriate shifting of a single platen face to different relationships in the successive printing cycles rather than by alternate shifting of two different platen faces into operative relationship in the successive cycles of the machine. In connection with the set up of the automatic platen mechanism it is important that the proper platen face PF be brought into printing cooperation with the lines of type characters to which such platen face pertains, and it is also important that automatic platen be so adjusted that the printing impressions made in the same line of the different columns be made from a single printing device. To this end the automatic platen mechanism is rendered operative at a time when the lister carriage 44 is in the position which it occupies at the time the last printing impression is made from a printing device. The multiprint mechanism 161 is also rendered operative at this same time. To facilitate the proper setting of the automatic platen mechanism, the setting may be verified or determined by means of the sight opening 173 through which index numbers on the cam and ratchet mechanism serve to indicate visually the number or other identification of the platen face which will be effective in the next printing operation.

The cams 350 and 351 are then set in the required angular relationship with respect to the path of transverse movement of the lister carriage 44, and this is readily accomplished while the lister is in position on the printing machine. In this connection it will be observed that all of the adjusting devices are located in conveniently accessible positions and are exposed for manipulation merely by removal of the cover 335. The angularity of the cams is, of course, governed in one sense by the column spacing dimension 115 of the form F. Since the column spacing 115 and the various line spacing and back spacing dimensions are known, the angularity of the two columns 350 and 351 may be readily determined. By loosening the screw and nut device 359 the line spacing cam 350 is released for shifting movement to such an angular relation that when the lister carriage is reciprocated through a stroke equal to the column spacing dimension 115, the line spacing slide 380 will be reciprocated through a stroke which is somewhat greater than the sum of the line spacing dimension 110 of the form F and the back spacing dimension 204. The back

spacing dimension is, of course, dependent upon the selection of lines to be printed from the printing device D and in a sense upon the spacing of such lines on the printing device.

5 The backspacing cam 351 is then released by loosening of the screw and nut device 361, and the angularity of the cam 351 is adjusted so that when the lister carriage 44 is reciprocated through a stroke equal to the column spacing dimension 115 of the form, the backspacing slide 250 will be reciprocated through a backspacing stroke equal to the back spacing dimension 204 of the printing device D. The two cams 350 and 351 are, of course, secured in these adjusted positions by tightening of the screw and nut devices 359 and 361. The shield 391 is then adjusted so that the pawls 385 are disabled at the end of the back spacing operation. The connection of the link 202 to the actuating lever 201 is, of course, adjusted so as to attain the desired transverse stroke of the lister carriage 44, and this end is attained through loosening of the nut 487 and through movement of the bearing structure 489 to a position where a stroke is attained. The nut 487 is then tightened to maintain this adjustment.

30 After the backspacing cam and the line spacing cam have been adjusted as aforesaid, the back spacing slide 480 will, at the end of each left-hand stroke of the lister carriage 44, come to rest at a particular point along the lister carriage 44, and when the line spacing slide 380 has come to rest at this point, the selected form F must be positioned so that the printing impression will be made in the desired relationship vertically in each of its lines. It will be recognized, of course, that a form F will in such an instance be mounted in the paper clamps 280 with the upper edge 97 of the form in engagement with the stop lugs 287, and after making a test impression, the location of the printing impression in a vertical sense in the line 105 may be suitably adjusted to the desired relationship through adjustment of the stud 312 along the longitudinal slot 311 of the flexible rack 310.

35 In some instances the adjustments which have been hereinbefore described with relation to the line spacing cam 350 and the back spacing cam 351 may produce an undesired location of the stroke of the back spacing carriage 250 with relation to its guideway, and this condition may be corrected through suitable adjustment of the stud 376 along the longitudinal slot in the mounting bracket 373. There may also be instances where the adjustment of the link 202 along the slot 480 may require a link 202 of a different length, and in such an instance a two part link such as the link 825, Fig. 29, may be employed.

40 After setting the machine up in the manner hereinbefore set forth a number of test impressions are made on a form, and the proper location of the form in the paper clamps 280 is determined so that the lateral positioning of the printing impressions in the two columns is properly attained. The side guide 285 is then put into position so that the forms may thereafter be quickly and easily mounted in position on the paper holder. In the making of the several test impressions the operator makes sure that the printing impressions in the second column are properly aligned in a horizontal sense with the printing impressions made in the first column. It will be observed that this adjustment or alignment may be extremely accurate in the present 45 lister since the paper holder 43 rides frictionally

upon a smooth guideway on the carrier 250, and the back spacing stroke may be varied in infinitely small increments to attain the desired accuracy of alignment. In the event that the impression in the second column is found to be lower than the impression in the first column, this condition may be corrected by increasing to a slight extent the angularity of the back spacing cam 351. Thus the conditioning movement of the back spacing carrier 250 is increased and as a result the back spacing movement imparted to the paper holder 43 is somewhat greater. Such alignment of the impressions in the two columns may be readily effected through but a few trial impressions and appropriate adjustments of the back spacing cam 351. If desired, an operator may make suitable index marks on the adjusting plate 354 to indicate selected positions of adjustment of the cams 350 and 351. The machine is then in condition for performance of the desired two column listing operations and such printing operations may be performed either through manual control of the printing machine by means of the various foot pedals 140, 141 and 142, or such operation may be performed under the control of the auto-stop means and its control plunger 180. Whether such control of the machine is to be attained manually or automatically, the selector means of the printing machine, under the control of the plunger 128, may be rendered effective to govern the print or skip operation of the printing machine in accordance with identifying means such as index tabs 65 carried on the printing devices.

When a form F is to be mounted in the paper holder 43, the forwardly projecting handle 400 of the paper carriage is grasped by the operator and the paper carriage is withdrawn in a forward direction. In the event that the lister of the carriage 44 is at the wrong end of its reciprocatory path, such improper location is immediately brought to the attention of the operator since the paths 485 will be engaged by the openings 320 in the flexible rack to restrain the paper holder against such forward withdrawing movement. If the lister carriage 44 is positioned in the lateral location which it occupies after the performance of the last printing operation in a particular line of the form F, the shield 391 is located so as to disable the pawls 385 and hence the paper holder may be freely withdrawn in a forward direction. Such forward withdrawing movement is, however, limited by engagement of the opening 403 in the flexible rack with the control pawl 402, such engagement serving to automatically determine the upper or top margin to be provided on the form F. The paper clamps 280 are opened through manipulation of the knob 295 and the paper is inserted between the paper clamps so that its upper edge 97 engages the lugs 287 of the paper clamps and the side guide 288 is engaged by the adjacent edge of the form. The paper clamps 280 are then permitted to close through suitable manipulation of the knob 295.

The apparatus is then in condition for performance of listing operations on the form F, and operation of the apparatus may be instituted through withdrawal of the auto-stop plunger 180. Upon such withdrawal of the auto-stop plunger the continuous operation of the printing machine is instituted and such continuous operation is modified only by the selector means of the printing machine, and by the multiprint mechanism which disables the printing device feeding means in alternate cycles of operation of

the printing machine. When a particular printing device is to be skipped, the selector shaft 520 is rocked to thereby throw the supplemental stop lever 156" and the supplemental stop lever 502 into their active positions. These supplemental stop levers prevent engagement of the platen clutch and the lister clutch, and hence the printing machine feeds the particular printing device through printing position without the performance of a printing operation therefrom. When the paper holder has been advanced until the last line 105 of the form F is brought into alignment with the printing position, the opening 431 of the flexible rack is concurrently aligned with the detecting pawl 410. The pawl 410 is, however, maintained inactive while the printing operation is being performed in the first column of the form F, such disabling action being attained by the cam 440. When the lister carriage 44 is shifted laterally in the next printing operation to position the second column of the form in alignment with printing position, the back spacing carrier 250 upon which the pawl 410 is mounted shifts in a forward direction so that the follower pin on the pawl 410 moves into alignment with the recess 445 on the cam 440, thereby to permit rocking movement of the detecting pawl 410 with a corresponding closure of the control switch 416. Closure of the control switch 416 serves to energize the auto-stop solenoid 181 to thereby stop the operation of the printing machine at the end of the cycle. Thus the printing operations performed with the lister of the present invention are confined to the margins provided on the form F.

The operation and adjustment of the lister embodying the manual spacing means, and the lister which provides for the performance of three column listing operations are substantially similar to the adjustment and operation hereinbefore described with relation to the two column embodiment of Figs. 1 to 20, since similar governing conditions are encountered in all of these embodiments.

Summary

It will be apparent from the foregoing description that the present invention provides a multiple column lister which is simple in form and is capable of meeting a wide variety of variable conditions which may be encountered in the commercial use of such devices. The multiple column lister of the present invention is readily and easily mounted on or removed from a printing machine so that such printing machine may be utilized for other types of printing operations during periods when the multiple column lister is not required. The lister is unitary in character and when it is removed from its operative association with respect to the printing machine, the adjustments which have been made in the lister are preserved, and hence the lister may be readily returned to its operative association with respect to the printing machine for the performance of further listing operations of the character for which it was previously adjusted. It will also be evident that the operative elements of the present lister are so constructed and arranged that all of the required adjustments may be readily and easily accomplished.

The multiple column lister of the present invention is such that the sequence in which the impressions are made in columns of a form may be readily reversed, and such reversal is attained merely through reversal of the parts of the lister

rather than through the substitution of other and differently formed parts. The present lister is adapted for convenient incorporation of means for obtaining manual line spacing of the form, and such modification for manual line spacing may be incorporated in either the two column or three column embodiments of the invention.

The lister of the present invention is such that the basic parts of the two column embodiment may be employed in producing an embodiment adapted for three column listing, and the mode of operation of the three column embodiment is substantially similar to the operation of the two column embodiment.

In all of its embodiments the present invention provides for automatically determining the top and bottom margins to be attained by the printing impressions on the form. The present multiple column lister also provides for convenient selection of any of the lines of type characters of a printing device for printing in the various columns of the forms, and such selection is in a sense independent of the line spacing to be employed on the form. Moreover, the upper line or lines of a printing device are first printed with the lister of the present invention, and selected material from the lower lines of the printing device, are then printed in another column of the form. The present invention provides a convenient means whereby backspacing movement may be imparted to the form after the printing of one or more upper lines of type from the printing device onto the form, and through this expedient the present multiple column lister is rendered unusually flexible in use.

The present invention provides a lister wherein in a wide variety of selection of lines for distribution in the columns of the form is afforded, and the lister is capable of convenient adjustment to attain different column spacings in the printed form. Hence the multiple column lister of the present invention is so constructed and arranged to satisfy a wide variety of variable conditions which may be encountered in its field of use.

While I have illustrated and described preferred embodiments of my invention it is to be understood that these are capable of variation and modification and I therefore do not wish to be limited to the precise details set forth but desire to avail myself of such changes and modifications as fall within the purview of the following claims.

I claim:

1. In a printing machine through which printing devices each bearing a plurality of groups of type characters are passed one by one to a printing position whereat impression means in the printing machine may operate in each of a plurality of printing operations performed with respect to each printing device to produce printed impressions from predetermined groups of type characters in succession, a multiple column lister associated with said printing machine and comprising a stationary lister frame, a lister carriage mounted on said frame for reciprocation transversely with respect to printing position, a paper holder mounted on said lister carriage for transverse movement therewith and for movement on and relative to said carriage longitudinally with respect to printing position, a pair of elongated cams mounted on said frame and disposed in different angular relationships with respect to the path of transverse reciprocation, means including a cam follower engaging one of said cams and operatively associated with said paper holder to

5 impart a predetermined longitudinal line spacing movement to said paper holder in an advancing direction when said lister carriage is shifted in one direction, and means including a cam follower engaging the other of said cams and operable upon said paper holder when said lister carriage is shifted in the other direction to impart to said paper holder a back spacing movement of a length which is independent of and different than the length of the line spacing movements.

2. In a printing machine through which printing devices each bearing a plurality of groups of type characters are passed one by one to a printing position whereat impression means in the printing machine may operate in each of a plurality of printing operations performed with respect to each printing device to produce printed impressions from different predetermined groups of type characters in succession, a multiple column lister associated with said printing machine and comprising a stationary lister frame, a lister carriage mounted on said frame for reciprocation transversely with respect to printing position, means providing a rectilinear guideway extending longitudinally of and carried by said lister carriage, a paper holder suspended on said guideway for transverse movement with said lister carriage and for movement on and relative to said carriage longitudinally with respect to printing position and along said guideway, a first cam means mounted on said lister frame and operatively associated with said paper holder to impart a predetermined longitudinal line spacing movement to said paper holder in an advancing direction when said lister carriage is shifted transversely in one direction, and a second cam means mounted on said lister frame and operatively associated with said paper holder to impart a different predetermined longitudinal back spacing movement to said paper holder in a reverse direction when said lister is shifted transversely in the other direction.

3. In a printing machine through which printing devices each bearing a plurality of groups of type characters are passed one by one to a printing position whereat impression means in the printing machine may operate in each of a plurality of printing operations performed with respect to each printing device to produce printed impressions from predetermined groups of type characters in succession, a multiple column lister associated with said printing machine and comprising a stationary lister frame at least a portion of which is disposed in overlying relation to the top of said printing machine, a lister carriage disposed so as to overlie the top of said printing machine at least in part and in upwardly spaced relation to said top, said carriage being mounted on said frame for reciprocation transversely with respect to printing position, a paper holder mounted on said lister carriage for transverse movement therewith and for movement on and relative to said carriage longitudinally with respect to printing position and through a total longitudinal range wherein said paper holder moves to a position in the space between said carriage and the top of said printing machine, and means mounted on said lister frame and operatively associated with said paper holder to impart a predetermined longitudinal line spacing movement to said paper holder in an advancing direction when said lister carriage is shifted transversely in one direction and when said lister carriage is shifted transversely in the

other direction to impart a somewhat smaller movement to said paper holder in a back spacing direction.

4. In a printing machine having a table top and through which printing devices each bearing a plurality of groups of type characters are passed one by one to a printing position in said table top whereat impression means in the printing machine may operate in each of a plurality of printing operations performed with respect to each printing device to produce printed impressions from predetermined groups of type characters in succession, a multiple column lister associated with said printing machine and comprising a stationary lister frame, a lister carriage mounted on said frame for reciprocation transversely with respect to printing position and arranged to overlie said table top in upwardly spaced relation to provide a clearance throat between a portion of said carriage and the top of said printing machine, a paper holder mounted on said lister carriage for transverse movement therewith and for movement on and relative to said carriage longitudinally with respect to printing position and into said clearance throat, and means mounted on said lister frame and operatively associated with said paper holder to impart predetermined line spacing and back spacing movements to said paper holder in accordance with the direction and extent of transverse movement of said lister carriage.

5. In a multiple column lister, a lister frame, a lister carriage mounted for transverse reciprocation on said frame, a paper holder in which a multi-column form having a predetermined line spacing may be mounted for transverse shifting movement to align the different columns with the printing position of a printing machine and for longitudinal shifting movement to align the successive lines of the form with such printing position, means supporting said paper holder on said lister carriage for transverse reciprocation therewith and for longitudinal shifting movement with relation to said carriage, an elongated member connected to said paper holder and extending along said carriage parallel to the path of longitudinal movement of said paper holder, actuating means operable in timed relation to the transverse shifting movement of said lister carriage to impart a predetermined back spacing movement to said paper holder when said lister carriage moves through its transverse stroke in one direction, and means operable in timed relation to the movement of said lister carriage when it moves through its stroke in the other direction to impart to said elongated member and hence to said paper holder an advancing movement equal to the sum of said back spacing movement and the line spacing dimension of the form.

6. In a multiple column lister, a lister frame, a lister carriage mounted for transverse reciprocation on said frame, a paper holder in which a multi-column form having a predetermined line spacing may be mounted for transverse shifting movement to align the different columns with the printing position of a printing machine and for longitudinal shifting movement to align the successive lines of the form with such printing position, means supporting said paper holder on said lister carriage for transverse reciprocation therewith and for longitudinal shifting movement with relation to said lister carriage, a pair of cams disposed on said lister frame above said carriage and in different angular relationships to the path of transverse reciprocation of said lister

carriage, actuating means including a cam follower operatively engaged with the one of said cams having the least angularity and operable in timed relation to the transverse shifting movement of said lister carriage to impart a predetermined back spacing movement to said paper holder when said lister carriage moves through its transverse stroke in one direction, and means including a cam roller operatively associated with the other of said cams and operable when said lister carriage moves through its stroke in the other direction to impart an advancing movement to said paper holder equal to the sum of said back spacing movement and the line spacing dimension of the form.

7. A printing machine through which a series of printing devices are adapted to be passed one by one to a printing position and having a printing machine frame providing outer side walls and a table top on said frame in which said printing position is located, impression means operable to produce printed impressions from a printing device at printing position, driving means for said impression means, and a multiple column lister comprising a lister frame, interengageable means on a lower portion of said lister frame and one of said outer walls of said printing machine frame for mounting said lister on said printing machine, said lister frame having an upstanding portion providing a guideway extending parallel to the lines of type characters of a printing device located at printing position, a lister carriage mounted on said guideway for transverse shifting movement through a predetermined stroke, means extending in part along said one of said outer walls and connecting said driving means to said lister carriage to impart such transverse reciprocation thereto, said lister carriage extending from said lister frame generally toward said printing position and in part over and in upwardly spaced relation to said table top, a paper holder mounted on and beneath said lister carriage for transverse movement therewith and for movement on and relative to said carriage longitudinally with respect to printing position, and means mounted on said lister frame above said lister carriage and operatively associated with said paper holder to impart a predetermined longitudinal line spacing movement to said paper holder in an advancing direction when said lister carriage is shifted in one direction and to impart a back spacing movement to said paper holder as said lister carriage is shifted in the other direction.

8. In a printing machine having a table top in which a printing position is provided, a multiple column lister associated with said printing machine and comprising a stationary lister frame extending over said table in spaced relation thereto, an elongated lister carriage mounted on said lister frame for reciprocation transversely with respect to printing position, an elongated back spacing carrier member mounted on said lister carriage for transverse movement therewith and for longitudinal reciprocation thereon, a paper holding member mounted on and beneath said carrier for transverse movement therewith and for movement on and relative to said carrier longitudinally with respect to printing position, a line spacing member mounted on said lister carriage for longitudinal reciprocation thereon, cam means mounted on said lister frame and operatively associated with said line spacing member and said carrier to reciprocate the line spacing member in timed re-

lation to the lateral reciprocation of said lister carriage, an elongated transmitting element extending between said line spacing member and said paper holding member, means connecting said element to one of said members, and means providing a one-way driving connection between said element and the other of said members to impart a predetermined longitudinal line spacing movement to said paper holding member in an advancing direction when said line spacing member is shifted in one direction.

9. In a printing machine having a table top in which a printing position is provided, a multiple column lister associated with said printing machine and comprising a stationary lister frame extending over said table in spaced relation thereto, an elongated lister carriage mounted on said lister frame in upwardly spaced relation to said table top and for reciprocation transversely with respect to printing position, an elongated back spacing carrier member mounted on said lister carriage for transverse movement therewith and for longitudinal reciprocation thereon, a paper holding member mounted on and beneath said carrier for transverse movement therewith and for movement on and relative to said carrier longitudinally with respect to printing position, a line spacing member mounted on said lister carriage for longitudinal reciprocation thereon, a pair of elongated cam means mounted on said lister frame over said lister carriage and operatively associated one with said line spacing member and the other with said carrier to reciprocate the same in timed relation to the lateral reciprocation of said lister carriage, an elongated transmitting element connected to said paper holding member and extending past said line spacing member, means providing a one-way driving connection between said element and said line spacing member to impart a predetermined longitudinal line spacing movement to said paper holding member in an advancing direction when said line spacing member is shifted in one direction, and means on said transmitting element operable to limit longitudinal movement of said paper holding member in one direction.

10. In a printing machine through which printing devices each bearing a plurality of groups of type characters are passed one by one to a printing position whereat impression means in the printing machine may operate in each of a plurality of printing operations performed with respect to each printing device to produce printed impressions from predetermined groups of type characters in succession, a distributing lister associated with said printing machine and comprising a stationary lister frame, a lister carriage mounted on said frame for reciprocation transversely with respect to printing position, a paper holder mounted on said lister carriage for transverse movement therewith and for movement on and relative to said carriage longitudinally with respect to printing position, a line spacing slide mounted on said lister carriage for longitudinal reciprocation thereon, cam means mounted on said lister frame and operatively associated with said line spacing slide to reciprocate the same in timed relation to the lateral reciprocation of said lister carriage, means providing a one-way driving connection between said line spacing slide and paper holder to impart a predetermined longitudinal line spacing movement to said paper holder in an advancing direction when said line spacing slide

is shifted in one direction, and actuated means on said lister frame having a frictional actuating connection with said paper holder for imparting other longitudinal movements to said paper holder.

11. In a distributing lister attachment for printing machines, a lister frame adapted for detachable association with the frame of such a printing machine, a lister carriage mounted on said lister frame for transverse reciprocation, a paper holder mounted on said lister carriage for longitudinal shifting movement therealong, means having a one-way driving connection with said paper holder and operable when said lister carriage is moved in one direction to impart a positive advancing movement to said paper holder in a line spacing direction, means rendered active when said lister carriage is shifted in the opposite direction along its path of transverse reciprocation and operable frictionally upon said paper holder to impart a back spacing movement to said paper holder.

12. In a printing machine through which printing devices each bearing a plurality of groups of type characters are passed one by one to a printing position whereat impression means in the printing machine may operate in each of a plurality of printing operations performed with respect to each printing device to produce printed impressions from predetermined different groups of type characters in succession, a multiple column lister associated with said printing machine and comprising a stationary lister frame, a lister carriage mounted on said frame for reciprocation transversely with respect to printing position, means for shifting said lister carriage back and forth transversely through a predetermined stroke at each end of which said lister carriage remains stationary for a dwell period providing time for the performance of a printing operation, a paper holder disposed beneath and mounted on said lister carriage for transverse movement therewith and for movement on and relative to said carriage longitudinally with respect to printing position, an elongated flexible rack connected to said paper holder and extending therefrom along said carriage, means mounted on said lister frame and arranged to operate in timed relation to the reciprocation of said lister carriage and to impart positive advancing movement to said paper holder in an advancing direction through positive engagement with said flexible rack, and additional means mounted on said lister carriage and operable in timed relation to the reciprocation of said lister carriage to impart a back spacing movement to said paper holder independently of said flexible rack.

13. In a multiple column lister, a lister frame, a lister carriage mounted for transverse reciprocation on said frame, a paper holder in which a multi-column form having a predetermined line spacing may be mounted for transverse shifting movement to align the different columns with the printing position of a printing machine and for longitudinal shifting movement to align the successive lines of the form with selected lines of type characters on a printing device located at such printing position, means supporting said paper holder on said lister carriage for transverse reciprocation therewith and for longitudinal shifting movement with relation to said lister carriage, and a pair of generally similar elongated cams disposed in horizontal posi-

tions above said lister carriage and mounted on said lister frame for individual adjustment to varying positions of angularity with relation to the path of transverse reciprocation of said lister carriage, means including a cam roller mounted for reciprocation transversely with and for longitudinal reciprocation on said lister carriage and operatively connected to said paper holder to impart a predetermined back spacing movement to said paper holder when said lister carriage moves through its transverse stroke in one direction, and means including a cam roller mounted for transverse reciprocation with and for longitudinal reciprocation on said lister carriage and operable when said lister carriage moves through its stroke in the other direction to impart an advancing movement to said paper holder equal to the sum of said back spacing movement and the line spacing dimension of the form.

14. In a multiple column lister attachment for printing machines, a lister frame adapted for detachable association with the frame of such a printing machine, a lister carriage mounted on said lister frame for transverse reciprocation, a back spacing carrier mounted on said lister carriage for transverse reciprocation with said carriage and for reciprocation through a relatively small stroke longitudinally of the lister carriage, a paper holder suspended beneath on said back spacing carrier for longitudinal shifting movement along said back spacing carrier, advancing means mounted on said lister carriage for reciprocatory movement and having a one-way driving connection with said paper holder operable when said lister carriage is moved in one direction to impart an advancing movement to said paper holder in a line spacing direction, and means operable during such advancing movement of the paper holder to impart a conditioning movement to said back spacing carrier in said line spacing direction, said last mentioned means being operable when said lister carriage is shifted in the opposite direction along its path of transverse reciprocation to impart a back spacing movement to said back spacing carrier and through said carrier to said paper holder.

15. In a multiple column lister attachment for printing machines, a lister frame adapted for detachable association with the frame of such a printing machine, a lister carriage mounted on said lister frame for transverse reciprocation, a back spacing carrier mounted on said lister carriage for transverse reciprocation with said carriage and for reciprocation through a relatively small stroke longitudinally of the lister carriage, a paper holder mounted on and carried by said back spacing carrier for longitudinal shifting movement along said back spacing carrier and normally tending to move with said back spacing carrier in its reciprocating movement, means operable when said lister carriage is moved in one direction to impart an advancing movement to said paper holder relative to said carrier in a line spacing direction, means operable during such advancing movement of the paper holder to impart a conditioning movement to said back spacing carrier in said line spacing direction, said last mentioned means being operable when said lister carriage is shifted in the opposite direction along its path of reciprocation to im-

part a back spacing movement to said back spacing carrier to thereby impart a back spacing movement to said paper holder.

16. In a multiple column lister, a lister frame, a lister carriage mounted for transverse reciprocation on said frame, a paper holder in which a multi-column form having predetermined column and line spacing dimensions may be mounted for transverse shifting movement with said paper holder to align the different columns with the printing position of a printing machine and for longitudinal shifting movement with said paper holder to align the successive lines of the form with such printing position, a line spacing member and a back spacing carrier mounted on said lister carriage for independent reciprocatory movement longitudinally of said lister carriage, means supporting said paper holder on said back spacing carrier for longitudinal sliding movement therealong, actuating means acting between said lister frame and said back spacing carrier and operable in timed relation to the transverse shifting movement of said lister carriage to impart a predetermined back spacing movement to said back spacing carrier when said lister carriage moves through its transverse stroke in one direction, actuating means acting between said lister frame and said line spacing member and operable when said lister carriage moves through its stroke in the other direction to impart an advancing movement to said line spacing member somewhat greater than the sum of said backspacing movement and the line spacing dimension of the form, and means forming a one-way driving connection between said line spacing member and said paper holder operable during a part of the stroke of said line spacing member in a line spacing direction to impart a line spacing movement to said paper holder equal to said sum of the line spacing dimension of said form and said back-spacing movement.

17. A multiple-column lister for use in association with a printing machine having a table top wherein a printing position is provided, said lister comprising a lister frame, an elongated lister carriage mounted on said lister frame for transverse reciprocation, a back spacing carrier mounted on and beneath said lister carriage for longitudinal reciprocation, a paper holder mounted on said back spacing carrier for longitudinal movement therealong, said back spacing carrier and said paper holder being arranged to move transversely with said lister carriage, said paper holder being mounted on said back spacing carrier so that throughout its entire range of movement it is located adjacent to one end of said carrier, a flexible actuating element secured to said paper holder and extending therefrom along said back spacing carrier to the point adjacent to the other end of said back spacing carrier, a coiling receptacle mounted on and carried by said back spacing carrier adjacent to said other end thereof and arranged to receive and coil the end of said flexible element as an incident to longitudinal actuation of said element towards said receptacle, a line spacing member mounted on said lister carriage for longitudinal reciprocation, means mounted on said lister frame and operable as an incident to transverse reciprocation of said lister carriage to impart different longitudinal movements to said back spacing carrier and said line spacing member, and means on said line spacing member interengageable with said flexible element to actuate the same toward said coiling receptacle.

18. In a printing machine through which print-

ing devices each bearing a plurality of groups of type characters are passed one by one to a printing position whereat impression means in the printing machine may operate in each of a plurality of printing operations performed with respect to each printing device to produce printed impressions from predetermined groups of type characters in succession, a multiple column lister associated with said printing machine and comprising a stationary lister frame, a lister carriage mounted on said frame for reciprocation transversely with respect to printing position, a paper holder mounted on said lister carriage for transverse movement therewith and for movement on and relative to said carriage longitudinally with respect to printing position, a line spacing slide mounted on said lister carriage for longitudinal reciprocation thereon, cam means mounted on said lister frame and operatively associated with said line spacing slide to reciprocate the same through a predetermined stroke in timed relation to the lateral reciprocation of said lister carriage, and means providing a one-way driving connection between said line spacing slide and said paper holder to impart a predetermined longitudinal line spacing movement to said paper holder in an advancing direction when said line spacing slide is shifted in one direction.

19. In a printing apparatus, a printing machine having a table top wherein a printing position is provided, a multiple column lister comprising a lister frame adapted to be secured on the frame of such a printing machine so as to be located at least in part above the level of the table top, an elongated lister carriage extending longitudinally with respect to said printing position and mounted on said lister frame for transverse reciprocation back and forth with respect to the printing position, a back spacing carrier mounted on and beneath said lister carriage for longitudinal reciprocation, a paper holder mounted on said back spacing carrier for longitudinal movement therealong, said back spacing carrier and said paper holder being arranged to move transversely with said lister carriage, and means carried on said lister frame for imparting longitudinal movement to said paper holder and to said back spacing carrier as an incident to transverse reciprocation of said lister carriage, said last mentioned means including an elongated member connected to said paper holder and extending therefrom along said back spacing carrier, and means engageable with said elongated member to actuate said paper holder in one direction, and means mounted on said back spacing carrier and adapted to cooperate with said elongated member to limit certain movements of said paper holder.

20. A multiple-column lister for use in association with a printing machine having a table top wherein a printing position is provided, said lister comprising a lister frame adapted to be secured on such a printing machine, an elongated lister carriage mounted on said lister frame for transverse reciprocation, a back spacing carrier mounted on said lister carriage for longitudinal reciprocation, a paper holder mounted on said back spacing carrier for longitudinal movement therealong, said back spacing carrier and said paper holder being arranged to move transversely with said lister carriage, said paper holder being mounted on said back spacing carrier beneath said carrier and adjacent to one end thereof, a flexible actuating element secured to said paper holder and extending therefrom along said back

spacing carrier to the point adjacent to the other end of said back spacing carrier, a coiling receptacle mounted on and carried by said back spacing carrier adjacent to said other end thereof and arranged to receive and coil the end of said flexible element as an incident to longitudinal actuation of said element towards said receptacle, a line spacing member mounted on said lister carriage for longitudinal reciprocation, means mounted on said lister frame and operable as an incident to transverse reciprocation of said lister carriage to impart different longitudinal movements to said back spacing carrier and said line spacing member, means on said line spacing member inter-engageable with said flexible element to actuate the same toward said coiling receptacle, and means on said back spacing member cooperating with said flexible element to limit movement of said flexible element and said paper holder in at least one direction.

21. In a printing apparatus, a printing machine having a table top wherein a printing position is provided, a multiple column lister comprising a lister frame adapted to be secured on said printing machine, an elongated lister carriage mounted on said lister frame for transverse reciprocation, a back spacing carrier mounted on said lister carriage for longitudinal reciprocation, a paper holder mounted on said back spacing carrier for longitudinal movement therealong, said back spacing carrier and said paper holder being arranged to move transversely with said lister carriage, said paper holder being mounted on said back spacing carrier adjacent to one end thereof, a flexible actuating element secured to said paper holder and extending therefrom along said back spacing carrier to the point adjacent to the other end of said back spacing carrier, a line spacing member mounted on said lister carriage for longitudinal reciprocation, means mounted on said lister frame and operable as an incident to transverse reciprocation of said lister carriage to impart different longitudinal movements to said back spacing member, means on said line spacing member inter-engageable with said flexible element to actuate the same in a line spacing direction, a spring pressed stop pawl mounted on said back spacing member and urged into contact with said flexible element, and said flexible element having a shoulder formed thereon for engagement by said pawl to limit movement of said flexible element and said paper holder in a back spacing direction.

22. In a printing apparatus, a printing machine having a table top wherein a printing position is provided, a multiple column lister comprising a lister frame adapted to be secured on said printing machine, an elongated lister carriage mounted on said lister frame for transverse reciprocation, a back spacing carrier mounted on said lister carriage for longitudinal reciprocation, a paper holder mounted on said back spacing carrier for longitudinal movement therealong, said back spacing carrier and said paper holder being arranged to move transversely with said lister carriage, said paper holder being mounted on said back spacing carrier adjacent to one end thereof, a flexible actuating element secured to said paper holder and extending therefrom along said back spacing carrier to the point adjacent to the other end of said back spacing carrier, a line spacing member mounted on said lister carriage for longitudinal reciprocation, means mounted on said lister frame and

operable as an incident to transverse reciprocation of said lister carriage to impart different longitudinal movements to said back spacing carrier and said line spacing member, means on said line spacing member inter-engageable with said flexible element to actuate the same in a line spacing direction, said flexible element having a pair of control openings formed therein in predetermined relation to the top and bottom margins desired on a selected form, and a pair of spring pressed pawls mounted on said back spacing carrier in different predetermined positions, one of said pawls being operable to engage one of said control openings to control movement of said paper holder in a back spacing direction, and the other of said pawls being engageable with the other of said control openings to detect predetermined movement of said paper holder in the other direction.

23. In a printing machine through which printing devices each bearing a plurality of groups of type characters are passed one by one to a printing position whereat impression means in the printing operations performed with respect to each printed device to produce printing impressions from predetermined groups of type characters in succession, a multiple column lister associated with said printing machine and comprising a stationary lister frame, a lister carriage mounted on said frame for reciprocation transversely with respect to printing position, a paper holder mounted on said lister carriage for transverse movement therewith and for movement on and relative to said carriage longitudinally with respect to printing position, a line spacing slide mounted on said lister carriage for longitudinal reciprocation thereon, cam means mounted on said lister frame and operatively associated with said line spacing slide to reciprocate the same in timed relation to the lateral reciprocation of said lister carriage, means providing a one-way driving connection between said line spacing slide and paper holder to impart a predetermined longitudinal line spacing movement to said paper holder in an advancing direction when said line spacing slide is shifted in one direction, and means operable upon said one way driving connection when said lister is at one end of its lateral reciprocating stroke to disable said connection and thereby enable said paper holder to be manually withdrawn in a back spacing direction.

24. In a printing machine through which printing devices each bearing a plurality of groups of type characters are passed one by one to a printing position whereat impression means in the printing machine may operate in each of a plurality of printing operations performed with respect to each printing device to produce printing impressions from predetermined groups of type characters in succession, a multiple column lister associated with said printing machine and comprising a stationary lister frame, a lister carriage mounted on said frame for reciprocation transversely with respect to printing position, a back spacing carrier mounted on said lister carriage for transverse movement therewith and for longitudinal reciprocation relative thereto, a paper holder mounted on said back spacing carrier for transverse movement therewith and for movement on and relative to said back spacing carrier longitudinally with respect to printing position, a line spacing slide mounted on said lister carriage for longitudinal reciprocation thereon, independently of said back spacing carrier, a line spacing cam mounted on said lister frame and

5 operatively associated with said line spacing slide to reciprocate the same in timed relation to the lateral reciprocation of said lister carriage, a back spacing cam mounted on said lister frame and operatively associated with said back spacing carrier to reciprocate said carrier in the same direction as said slide but through a shorter stroke in timed relation to the lateral reciprocation of said lister carriage, means providing a one-way driving connection between said line spacing slide and said paper holder to impart a predetermined longitudinal line spacing movement to said paper holder in an advancing direction when said line spacing slide is shifted in one direction, said paper holder being carried with said back spacing carrier when the carrier moves in its back spacing direction to thereby attain a back spacing movement, and means carried by said back spacing carrier and operable upon said one-way driving connection when said back spacing movement has been completed to disable said one-way driving connection and thereby enable said paper holder to be manually withdrawn in a back spacing direction.

25. In a multiple column lister, a lister frame, a lister carriage mounted for transverse reciprocation on said frame, a paper holder in which a multi-column form having predetermined column and line spacing dimensions may be mounted for transverse shifting movement with said paper holder to align the different columns with the printing position of a printing machine and for longitudinal shifting movement to align the successive lines of the form with such printing position, a line spacing member and a back spacing carrier mounted on said lister carriage for independent reciprocatory movement longitudinally of said lister carriage, means supporting said paper holder on said back spacing carrier for longitudinal sliding movement therealong, actuating means acting between said lister frame and said back spacing carrier and operable in timed relation to the transverse shifting movement of said lister carriage to impart a predetermined back spacing movement to said back spacing carrier when said lister carriage moves through its transverse stroke in one direction, actuating means acting between said lister frame and said line spacing member and operable when said lister carriage moves through its stroke in the other direction to impart an advancing movement to said line spacing member somewhat greater than the sum of said back spacing movement and the line spacing dimension of the form, 55 means forming a one-way driving connection between said line spacing member and said paper holder operable during a part of the stroke of said line spacing member in a line spacing direction to impart a line spacing movement to said paper holder equal to said sum of the line spacing dimension of said form and said back spacing movement, and means operable at the end of a back spacing movement to disable said one-way driving connection and thereby enable said paper holder to be withdrawn freely in a back spacing direction.

26. In a printing machine having a table top in which a printing position is provided, a multiple column lister having a lister frame mounted on said printing machine, a lister carriage mounted for transverse reciprocation on said frame, a paper holder in which a multi-column form having a predetermined line spacing and a predetermined column spacing may be mounted 70 for transverse shifting movement to align the

different columns with the printing position of the printing machine and for longitudinal shifting movement to align successive lines of the form with selected lines of type characters on a printing device at printing position, means supporting said paper holder on said lister carriage for transverse reciprocation with said lister carriage and for longitudinal shifting movement with relation to said lister carriage, means for reciprocating said lister carriage through a predetermined stroke, means operable as an incident to such transverse reciprocation of said lister carriage to impart longitudinal movements to said paper holder, and a plurality of horizontally spaced vertically resilient snubber devices mounted on said paper holder and having lower rounded surfaces riding over and along the table top to stabilize said paper holder as it is shifted transversely and longitudinally.

27. In a printing machine having a table top in which a printing position is provided, a multiple column lister associated with said printing machine and comprising a stationary lister frame extending over said table in spaced relation thereto, an elongated lister carriage mounted on said lister frame for reciprocation transversely with respect to printing position, an elongated back spacing carrier member mounted on said lister carriage for transverse movement therewith and for longitudinal reciprocation thereon, a paper holding member mounted on and beneath said carrier for transverse movement therewith and for movement on and relative to said carrier longitudinally with respect to printing position, a line spacing member mounted on said lister carriage for longitudinal reciprocation thereon, cam means mounted on said lister frame and operatively associated with said line spacing member and said carrier to reciprocate the same in timed relation to the lateral reciprocation of said lister carriage, an elongated transmitting element extending between said line spacing member and said paper holding member, means connecting said element to one of said members, means providing a one-way driving connection between said element and the other of said members to impart a predetermined longitudinal line spacing movement to said paper holding member in an advancing direction when said line spacing member is shifted in one direction, and means operable upon said one-way driving connection when said lister carriage is at one end of its lateral reciprocating stroke to disable said connection and thereby enable said paper holding member to be manually withdrawn in a back spacing direction.

28. A printing machine having a printing position and impression means at said printing position, a paper holder for locating a form in the desired relationship to said printing position, means supporting said paper holder for longitudinal movement relative to said printing position, an elongated transmitting member connected to said paper holder and extending parallel to the path of such longitudinal movement of said paper holder, said member having shoulders formed thereon at longitudinally spaced points, a feeding mechanism adapted to engage said shoulders to feed said member and said paper holder in one longitudinal direction, said elongated member having a longitudinally extending control area spaced laterally from said shoulders, said longitudinally extending control area embodying indicia in predetermined relationship to said paper holder, and means adapted to cooperate

with said indicia to limit movement of said transmitting member and thereby determine one of the margins of a form.

29. A printing machine having a printing position and impression means at said printing position, a paper holder for locating a form in the desired relationship to said printing position, means supporting said paper holder for longitudinal movement relative to said printing position, 5 an elongated transmitting member connected to said paper holder and extending parallel to the path of such longitudinal movement of said paper holder, said member having shoulders formed thereon at longitudinally spaced points, 10 a feeding mechanism adapted to engage certain of said shoulders to feed said member and said paper holder in one longitudinal direction, said elongated member having a longitudinally extending control area spaced laterally from said shoulders, said longitudinally extending control area control indicia at longitudinally spaced points in different predetermined relationships to said paper holder, means adapted to cooperate with one of said indicia to determine one of the margins of a form, and means adapted to cooperate with the other of said indicia to limit movement of said transmitting member and thereby determine the opposite one of the margins of a form.

30. A printing machine having a printing position and impression means at said printing position, a paper holder for locating a form in the desired relationship to said printing position, means supporting said paper holder for longitudinal movement relative to said printing position, 35 an elongated flexible strip connected to said paper holder and extending parallel to the path of such longitudinal movement of said paper holder, said strip having shoulders formed thereon at longitudinal spaced points, a feeding mechanism adapted to engage said shoulders to feed said strip and said paper holder in one longitudinal direction, said elongated strip having one longitudinal area spaced laterally from said shoulders and adapted to be utilized for purposes of control, 40 said longitudinally extending area having an opening formed therein in predetermined relationship to said paper holder, and means adapted to be engaged with said opening to limit movement of said transmitting member and thereby determine one of the margins of a form.

31. A printing machine having a printing position and impression means at said printing position, a paper holder for locating a form in the desired relationship to said printing position, means supporting said paper holder for longitudinal movement relative to said printing position, an elongated flexible strip connected to said paper holder and extending parallel to the path of such longitudinal movement of said paper holder, said strip having shoulders formed thereon at longitudinally spaced points, a feeding mechanism adapted to engage certain of said shoulders to feed said strip and said paper holder in one longitudinal area spaced laterally from said shoulders and adapted to be utilized for purposes of control, 55 said longitudinally extending area having a pair of spaced openings formed therein in different predetermined relationships to said paper holder, means adapted to engage with one of said openings to limit movement of said transmitting member in one direction and thereby determine one of the margins of a form, and means adapted to engage with the other of said openings to limit movement of said transmitting

ting member in the other direction and thereby determine the opposite one of the margins of a form.

32. An elongated flexible member for actuating the paper holder of a listing mechanism, said elongated member having an elongated actuating area and an elongated control area, said flexible member in said actuating area having a plurality of shoulders formed thereon in predetermined longitudinally spaced relationship, and said flexible member in said elongated control area having at least one opening, the position of which constitutes an indication of position of a paper holder to which the elongated member is connected.

33. An elongated flexible member for actuating the paper holder of a listing mechanism, said elongated member having an elongated actuating area and an elongated control area, said flexible member in said actuating area having a plurality of shoulders formed in predetermined longitudinally spaced relationship, and said flexible member in said elongated control area having a pair of openings spaced longitudinally of said control area, the positions of said openings constituting indications of critical positions of a paper holder to which the elongated member is connected.

34. In a printing machine having the printing position and impression means located at said printing position, a lister mechanism including a paper holder in which a form having predetermined top and bottom margins may be clamped for longitudinal movement with said paper holder and across said printing position, and means for imparting such longitudinal movement to said paper holder comprising an elongated flexible member connected to said paper holder and extending therefrom in a direction parallel to the longitudinal advancing movement of said paper holder, reciprocable actuating means operable through its reciprocating stroke along the path adjacent to said flexible member, said flexible member having means formed thereon adapted to be engaged by said actuating means to impart advancing movement to said paper holder, and means for determining the bottom margin of such a form, comprising a detecting member, means responsive to the operation of said detecting member for stopping operation of said actuating means, and means formed on said flexible member in a position to be engaged by said detecting member when the bottom margin portion of said form has been advanced into a predetermined relationship to said printing position.

35. In a printing machine having the printing position and impression means located at said printing position, a lister mechanism including a paper holder to which a form having predetermined top and bottom margins may be clamped for longitudinal movement with said paper holder and across said printing position, means for imparting such longitudinal movement to said paper holder comprising an elongated flexible member connected to said paper holder and extending therefrom in a direction parallel to the longitudinal advancing movement of said paper holder, reciprocably actuating means operable through its reciprocating stroke along the path adjacent to said flexible member, said flexible member having means formed thereon adapted to be engaged by said actuating means to impart advancing movement to said paper holder, means for determining the bottom margin of such a form com-

prising a detecting member, means responsive to the operation of said detecting member for stopping operation of said actuating means, and means formed on said flexible member in a position to be engaged by said detecting member when the bottom margin portion of said form has been advanced into a predetermined relationship to said printing position, means for withdrawing said paper holder in a back spacing direction to a loading position, and cooperating means on said lister carriage and on said flexible member adapted for inter-engagement to limit such manual withdrawing movement of said paper holder and thereby determine the top margin on the form.

36. In a multiple column lister, a lister frame, a lister carriage mounted for transverse reciprocation on said frame, a paper holder in which a multi-column form having predetermined column and line spacing dimensions and predetermined bottom and top margin dimensions may be mounted for transverse shifting movement with said paper holder to align the different columns with the printing position of a printing machine and for longitudinal shifting movement to align the successive lines of the form with such printing position, a line spacing member and a back spacing carrier mounted on said lister carriage for independent reciprocatory movement longitudinally of said lister carriage, means supporting said paper holder on said back spacing carrier for longitudinal sliding movement therealong, actuating means acting between said lister frame and said back spacing carrier and operable in timed relation to the transverse shifting movement of said lister carriage to impart a predetermined back spacing movement to said back spacing carrier when said lister carriage moves through its transverse stroke in one direction, actuating means acting between said lister frame and said line spacing member and operable when said lister carriage moves through its stroke in the other direction to impart a line spacing movement to said line spacing member, a flexible element mounted on said back spacing carrier and connected to said paper holder for actuating the same in a line spacing direction, means forming a one-way driving connection between said line spacing member and said flexible element operable during at least a part of the stroke of said line spacing member in a line spacing direction to impart a line spacing movement to said paper holder, and cooperating means on said back spacing carrier and said flexible element operable to determine at least one of said margins.

37. A printing apparatus comprising a printing machine through which a series of printing devices each bearing a plurality of lines of printing characters are adapted to be passed one by one to a printing position and having a printing machine frame providing vertical outer walls, and a table top on said frame in which said printing position is located, impression means operable in a succession of operative cycles thereof to produce printed impressions from different lines of type characters of a printing device at printing position, driving means for said impression means, and a multiple column lister comprising a lister frame, inter-engageable means on a lower portion of said lister frame and one of said outer walls of said printing machine frame for detachably mounting said lister on said printing machine, said lister frame having an upstanding portion providing a guideway extending parallel to the lines of type characters of

a printing device located at printing position, a lister carriage mounted on said guideway for transverse shifting movement through a predetermined stroke, means extending in part along said one of said outer walls and connecting said driving means to said lister carriage to impart such transverse reciprocation thereto, a paper holder mounted on said lister carriage for transverse movement therewith and for movement on and relative to said carriage longitudinally with respect to printing position, and means mounted on said lister frame and operatively associated with said paper holder to impart a predetermined longitudinal line spacing movement to said paper holder in an advancing direction and to impart a back spacing movement to said paper holder as said lister carriage is shifted in the other direction.

38. A printing apparatus comprising a printing machine through which a series of printing devices each bearing a plurality of lines of printing characters are adapted to be passed one by one to a printing position and having a printing machine frame providing vertical outer walls, and a table top on said frame in which said printing position is located, impression means operable in a succession of operative cycles thereof to produce printed impressions from different lines of type characters of a printing device at printing position, driving means for said impression means, and a multiple column lister comprising a lister frame, inter-engageable means on a lower portion of said lister frame and one of said outer walls of said printing machine frame for detachably mounting said lister on said printing machine, said lister frame having an upstanding portion providing a guideway extending parallel to the lines of type characters of a printing device located at printing position, a lister carriage mounted on said guideway for transverse shifting movement through a predetermined stroke, means extending in part along said one of said outer walls and connecting said driving means to said lister carriage to impart such transverse reciprocation thereto, a paper holder mounted on said lister carriage for transverse movement therewith and for movement on and relative to said carriage longitudinally with respect to printing position, and means mounted on said lister frame and operatively associated with said paper holder to impart a predetermined longitudinal movement to said paper holder to shift a form carried by said holder into different positions of alignment as the lister carriage is shifted in opposite directions.

39. A multiple-column lister for use in association with a printing machine having a table top wherein a printing position is provided, said lister comprising a pair of spaced side frame members adapted to be secured on one side wall of the frame of such a printing machine and to extend upwardly in spaced relation to a point above the level of the table top, connecting rails extending transversely between and fixed to said side frame members to maintain the same in a rigid and spaced relationship, an elongated lister carriage extending longitudinally with respect to said transverse connecting rails, and mounted on certain of said rails for transverse reciprocation back and forth in the space between said side frame members, a back spacing carrier mounted on and beneath said lister carriage for longitudinal reciprocation, a paper holder mounted on said back spacing carrier for longitudinal movement there-

along, said back spacing carrier and said paper holder being arranged to move transversely with said lister carriage, and means carried on one of said mounting rails for imparting longitudinal movement to said paper holder and reciprocating movement to said back spacing carrier as an incident to transverse reciprocation of said lister carriage.

40. A multiple-column lister for use in association with a printing machine having a table top wherein a printing position is provided, said lister comprising a pair of spaced side frame members adapted to be secured on one side wall of the frame of such a printing machine and to extend upwardly in spaced relation to a point above the level of the table top, connecting rails extending transversely between and fixed to said side frame members to maintain the same in a rigid and spaced relationship, an elongated lister carriage extending longitudinally with respect to said transverse connecting rails, and mounted on certain of said rails for transverse reciprocation back and forth in the space between said side frame members, a paper holder mounted on and beneath said lister carriage for longitudinal movement therewith, said paper holder being arranged to move transversely with said lister carriage, and means carried on one of said mounting rails for imparting longitudinal movements to said paper holder as an incident to transverse reciprocation of said lister carriage.

41. A multiple-column lister for use in association with a printing machine having a table top wherein a printing position is provided, said lister comprising a pair of spaced side frame members adapted to be secured on one side wall of the frame of such a printing machine and to extend upwardly in spaced relation to a point above the level of the table top, connecting rails extending transversely between and fixed to said side frame members to maintain the same in a rigid and spaced relationship, an elongated lister carriage extending longitudinally with respect to said transverse connecting rails, and mounted on certain of said rails for transverse reciprocation back and forth in the space between said side frames, a back spacing carrier mounted on and beneath said lister carriage for longitudinal reciprocation, a paper holder mounted on said back spacing carrier for longitudinal movement therewith, said back spacing carrier and said paper holder being arranged to move transversely with said lister carriage, said paper holder being mounted on said back spacing carrier adjacent to one end thereof, a flexible actuating element secured to said paper holder and extending therefrom along said back spacing carrier to a point adjacent to the other end of said back spacing carrier, a coiling receptacle mounted on and carried by said back spacing carrier adjacent to said other end thereof and arranged to receive and coil the end of said flexible element as an incident to longitudinal actuation of said element towards said receptacle, a line spacing member mounted on said lister carriage for longitudinal reciprocation, means mounted on one of said connecting rails and operable as an incident to transverse reciprocation of said lister carriage to impart different longitudinal movements to said back spacing carrier and said line spacing member, and means on said line spacing member inter-engageable with said flexible element to actuate the same toward said coiling receptacle.

42. In a multiple column lister, a lister frame, 75 a lister carriage mounted for transverse recipro-

cation on said frame, a paper holder in which a multi-column form having a predetermined line spacing may be mounted for transverse shifting movement to align the different columns with the printing position of a printing machine and for longitudinal shifting movement to align different columnar portions of the successive lines of the form with selected lines of type characters on a printing device located at such printing position, means supporting said paper holder on said lister carriage for transverse reciprocation therewith and for longitudinal shifting movement with relation to said lister frame, and a pair of generally similar elongated cams mounted in horizontal positions on said lister frame in different positions of angularity with relation to the path of transverse reciprocation of said lister carriage, means including a cam roller engaged with one of said cams and mounted for reciprocation on said lister carriage and operatively connected to said paper holder to impart a predetermined back spacing movement to said paper holder when said lister carriage moves through its transverse stroke in one direction, and line spacing means including a cam roller engaged with the other of said cams and mounted for transverse reciprocation with and for longitudinal reciprocation on said lister carriage and operable when said lister carriage moves through its stroke in the other direction to impart an advancing movement to said paper holder equal to the sum of said back spacing movement and the line spacing dimension of the form, and means for actuating said line spacing means while said lister carriage is stationary to impart a line spacing movement to said paper holder.

43. In a multiple column lister, a lister frame, a lister carriage mounted for transverse reciprocation on said frame, a line spacing member and a back spacing carrier mounted on said lister carriage for independent reciprocatory movement longitudinally of said lister carriage, a paper holder supported on said back spacing carrier for longitudinal sliding movement therealong, actuating means acting between said lister frame and said back spacing carrier and operable in timed relation to the transverse shifting movement of said lister carriage to impart a predetermined back spacing movement to said back spacing carrier when said lister carriage moves through its transverse stroke in one direction, actuating means comprising an elongated cam supported on said lister frame in an angular relation to the path of transverse reciprocation of said lister carriage and a cam roller mounted on said line spacing member and engaging said cam, said cam and cam roller being operable when said lister carriage moves through its stroke in the other direction to impart an advancing movement to said line spacing member, means forming a one-way driving connection between said line spacing member and said paper holder operable during a part of the stroke of said line spacing member in a line spacing direction to impart a line spacing movement to said paper holder, said cam being formed in such a manner that said line spacing member may be actuated in a line spacing direction independently of said cam, spring means acting to urge said cam roller against said cam, and manually operable means mounted on said lister carriage, and operable to impart line spacing movement to said line spacing member.

44. In a printing machine through which printing devices are passed one by one to a print-

ing position whereat impression means in the printing machine may operate to produce printing impressions from said printing devices, a multiple column lister associated with said printing machine and comprising a stationary lister frame, a lister carriage mounted on said frame for reciprocation transversely with respect to printing position, a paper holder mounted on said lister carriage for transverse movement therewith and for movement on and relative to said carriage longitudinally with respect to printing position, an elongated cam mounted on said lister frame, and having a cam surface disposed at an angle to the transverse path of said lister carriage, means including a cam follower operatively associated with said paper holder to impart a longitudinal line spacing movement to said paper holder in an advancing direction as said cam follower is actuated by said cam during movement of said lister carriage in one direction, said cam surface being formed as one side of a cam slot of varying width, spring means urging said cam roller into contact with said cam surface, and manual line spacing means connected to said cam roller and operable to impart a line spacing movement to said cam roller when said cam roller is located in a wide portion of said slot.

45. In a printing machine through which printing devices are passed one by one to a printing position whereat impression means in the printing machine may operate to produce printing impressions from said printing devices, a multiple column lister associated with said printing machine and comprising a stationary lister frame, a lister carriage mounted on said frame for reciprocation transversely with respect to printing position, a paper holder mounted on said lister carriage for transverse movement therewith and for movement on and relative to said carriage longitudinally with respect to printing position, an elongated cam mounted on said lister frame, and having a cam surface disposed at an angle to the transverse path of said lister carriage, means including a cam follower operatively associated with said paper holder to impart a longitudinal line spacing movement to said paper holder in an advancing direction as said cam follower is actuated by said cam during movement of said lister carriage in one direction, said cam surface being formed as one side of a cam slot of varying width, such that the slot is relatively wide at one end thereof and is relatively narrow at the other end thereof, spring means urging said cam roller into contact with said cam surface, and manual line spacing means connected to said cam roller and operable to impart a line spacing movement to said cam roller when said cam roller is located in a wide portion of said slot.

46. In a multiple column lister, a lister frame, a lister carriage mounted for transverse reciprocation on said frame, a paper holder in which a multi-column form having a predetermined line spacing may be mounted for transverse shifting movement to align the different columns with the printing position of a printing machine and for longitudinal shifting movement to align the successive lines of the form with selected lines of type characters on a printing device located at such printing position, means supporting said paper holder on said lister carriage for transverse reciprocation therewith and for longitudinal shifting movement with relation to said

lister carriage, and a pair of generally similar elongated cams disposed in horizontal positions on said lister frame for individual adjustment to varying positions of angularity with relation to the path of transverse reciprocation of said lister carriage, a cam-mounting plate secured disposed on said lister carriage adjacent one side thereof and upon which corresponding ends of said cams are pivoted, an adjusting plate disposed on said lister carriage adjacent the other edge thereof and to which the other ends of said cams are adjustably secured, means including a cam roller mounted for reciprocation transversely with and for longitudinal reciprocation on said lister carriage and operatively connected to said paper holder to impart a predetermined back spacing movement to said paper holder when said lister carriage moves through its transverse stroke in one direction, and means including a cam roller mounted for reciprocation with and for longitudinal reciprocation on said lister carriage and operable when said lister carriage moves through its stroke in the other direction to impart an advancing line spacing movement to said paper holder, and means securing said mounting plate and said adjusting plate on said lister carriage constructed and arranged for reversal of the relationship of said plates and said cams with respect to said lister carriage whereby to provide for reversal of the sequence of longitudinal paper holder movements with relation to the movements of said lister carriage.

47. In a printing machine through which printing devices are passed one by one to a printing position whereat impression means in the printing machine may operate to produce printed impressions from said printing devices a multiple column lister associated with said printing machine and comprising a stationary lister frame, a lister carriage mounted on said frame for reciprocation transversely with respect to printing position, a back spacing carrier mounted on said lister carriage for transverse movement therewith and for longitudinal reciprocation relative thereto, a paper holder mounted on said back spacing carrier for transverse movement therewith and for movement on and relative to said back spacing carrier longitudinally with respect to printing position, a line spacing slide mounted on said lister carriage for longitudinal reciprocation thereon, independently of said back spacing carrier, a line spacing cam disposed on said lister frame and operatively associated with said line spacing slide to reciprocate the same in timed relation to the lateral reciprocation of said lister carriage, a back spacing cam disposed on said lister frame and operatively associated with said back spacing carrier to reciprocate said carrier in the same direction as said slide but through a shorter stroke in timed relation to the lateral reciprocation of said lister carriage, means providing a one-way driving connection between said line spacing slide and paper holder to impart a predetermined longitudinal line spacing movement to said paper holder in an advancing direction when said line spacing slide is shifted in one direction, said paper holder being carried with said back spacing carrier when the carrier moves in its back spacing direction to thereby attain a back spacing movement, and means mounting said cams on said lister carriage for reversal of their angular positions to thereby enable the sequence of line spacing and back spacing movements of said paper holder

to be reversed with relation to the reciprocatory movements of said lister carriage.

48. In a three-column lister, a lister frame, a lister carriage mounted for transverse reciprocation on said frame, a paper holder in which a three-column form having a predetermined line spacing may be mounted for transverse shifting movement to align the different columns in predetermined succession with the printing position of a printing machine and for longitudinal shifting movement to align the different columnar portions of the successive lines of the form with different selected lines of type characters on a printing device located at such printing position for the production of printed impression from the selected lines of type characters in the predetermined columnar portions to which such lines have been selectively allocated, means supporting said paper holder on said lister carriage for transverse reciprocation therewith and for longitudinal shifting movement with relation to said lister carriage, and a pair of generally similar elongated cams mounted in horizontal positions on said lister frame in different positions of angularity with relation to the path of transverse reciprocation of said lister carriage, means including a cam roller engaging a first one of said cams and mounted for reciprocation transversely with and for longitudinal reciprocation on said lister carriage and operatively connected to said paper holder to impart a predetermined back spacing movement to said paper holder in accordance with the form of said first cam when said lister carriage moves through its transverse stroke in a first direction, and means including a cam roller engaged with the other of said cams and mounted for reciprocation with and for longitudinal reciprocation on said lister carriage and operable when said lister carriage moves through its stroke in a second and opposite direction to impart advancing movement to said paper holder, means for actuating said lister carriage through a reciprocating stroke wherein dwell periods are afforded in succession at one end of the stroke, at a medial point, and at the other end of the stroke, said other cam being operable when the carriage is shifted to said medial dwell position to impart a line spacing movement to said paper holder equal to the sum of the line spacing of said form plus the line spacing of predetermined lines of said printing device, said other cam being also operable as said carriage is shifted from said medial dwell position to the other of said end dwell positions to impart a line spacing movement to said paper holder equal to the line spacing of other lines on said printing device, and said first one of said cams being operable when said carriage is shifted back to said first one of said end dwell positions to impart a back spacing movement to said paper holder equal to the sum of the two aforesaid line spacing dimensions of said printing device.
49. In a three-column lister attachment for printing machines, a lister frame adapted for detachable association with the frame of such a printing machine, a lister carriage mounted for transverse reciprocation on said frame, a paper holder mounted on said lister carriage for transverse reciprocation therewith to first, second and third transverse positions to align the successive columns of a three-column form carried in said paper holder successively with the printing position of such a printing machine, said paper holder being mounted on said lister carriage

for longitudinal shifting movement relative to said carriage to align selected portions of said columns with selected lines of type characters embodied in a printing device located at printing position, means for actuating said lister carriage to said first, second and third positions in succession, and means mounted on said lister frame and operable solely in response to transverse reciprocation of said lister carriage to impart a longitudinal movement of one character to said paper holder when said lister carriage is moved between said first and second positions, to impart a longitudinal movement of another character to said paper holder when said carriage is moved from said second position to said third position, and to impart a longitudinal movement of still another character to said paper holder when said lister carriage is moved from said third position to said first position.

50. In a printing machine through which printing devices are passed one by one to a printing position whereat impression means in the printing machine may operate to produce printed impressions from said printing devices, a three-column lister associated with said printing machine and comprising a stationary lister frame, a lister carriage mounted on said frame for re-

ciprocation transversely with respect to printing position, means for shifting said lister carriage to first, second and third transverse positions in predetermined succession such that at each 5 of said positions said lister carriage remains stationary for a dwell period providing time for the performance of a printing operation, a paper holder mounted on said lister carriage for transverse movement therewith and for movement on and relative to said carriage longitudinally with respect to printing position, and actuating means including cam means and cooperating cam follower means mounted on said lister frame and operatively associated with said 10 paper holder to impart one predetermined longitudinal movement to said paper holder when said lister carriage is shifted from said first position to said second position, to impart another predetermined longitudinal movement to said 15 paper holder when said lister carriage is moved from said second position to said third position, and to impart still another predetermined longitudinal movement to paper holder when said lister carriage is moved from said third position to said first position.

CARL J. HUEBER.
